27 Claims. (Cl. 70—135)

This invention relates to improvements in a lock and more particularly to a free-handle lock for an automobile door.

An object of the present invention is to provide a door lock that will operate satisfactorily under all conditions of usage with no jamming or smash up of its component parts, that has an outside handle which can be freely moved between actuated and unactuated positions after the door is closed and locked without permitting this movement to unlatch the door, that automatically delocks the door on closing with the outer handle held in either the actuated, unactuated or any intermediate position, and/or that has a controlled toggle linkage operable during locking, unlocking and/or automatic rotor delocking of the door.

A further object of the present invention is to provide a lock characterized by its structural simplicity, operating efficiency, inexpensive manufacturing cost, ease of assembly, strong and sturdy nature, and ease of operation.

Other features of this invention reside in the arrangement and design of the parts for carrying out their appropriate functions.

Other objects and advantages of this invention will be apparent from the accompanying drawings and description and the essential features will be set forth in the appended claims.

In the drawings,

FIG. 1 is a schematic side elevational view with portions cut away of an automobile door and a portion of the body with a first form of the lock of the present invention mounted in the front door and with the actuating linkages, handles and lock key cylinder shown schematically;

FIG. 2 is a plan view of the rotor face of the lock with the component parts thereof shown in solid line in their unlocked and unactuated position with the door handles relaxed and with a key actuated locking link in unlocking position and with the component parts shown in dot-dash line in the unlocked and actuated position with both inner and outer handle operated components in their actuated position to permit door opening;

FIG. 3 is a vertical sectional view taken generally along the line 3—3 of FIG. 2;

FIG. 4 is a vertical sectional view taken along the line 4—4 of FIG. 2;

FIG. 5 is a vertical sectional view taken along the line 5—5 of FIG. 4;

FIG. 6 is a sectional view taken along the line 6—6 of FIG. 3;

FIG. 7 is a longitudinal sectional view taken along the line 7—7 of FIG. 2 through a control link;

FIG. 8 is a bottom view of the lock shown in FIG. 2;

FIG. 9 is a plan view, corresponding to FIG. 2, but with the lever and link, shown in FIG. 10, omitted for clarity and with the component parts shown in solid line in the locked and unactuated position with the outside handle in the relaxed or unactuated position and with the key actuated locking link locked or actuated and is shown in dot-dash lines in the locked and actuated position with the outside handle in the actuated position;

FIG. 10 is a vertical sectional view taken generally along the line 10—10 of FIG. 9 with the inside handle controlled linkage in unactuated position in solid line and in dot-dash line in locking position;

2

FIG. 11 is a plan view, corresponding to FIG. 2, but with the lever and link, shown in FIG. 12, omitted for clarity and with the component parts in an intermediate position during the rotor delocking action shown in solid line position when the outside handle is held in actuated position during door closing and shown in dot-dash line position when the outside handle remains in non-actuated position during door closing;

FIG. 12 is a vertical sectional view taken generally along the line 12—12 of FIG. 11 showing the control lever in the solid line, neutral, and unactuated position corresponding with both solid and dash line positions of FIG. 11;

FIG. 13, located to the left of FIG. 1, is an enlarged schematic view of a portion of FIG. 1 with a second form of the lock substituted therein;

FIG. 14 is a sectional view, taken generally along line 14—14 of FIG. 15 through the plate portion but with the lever, pivot and slide shown in edge view in solid lines, of the rotor face of the lock in FIG. 13 with a portion of the cover plate cut away and its remaining outline shown in dot-dash lines and with the component parts thereof shown in solid line in their unlocked and unactuated position with the door handles relaxed and with a key actuated locking link in unlocking position and with the component parts shown in dot-dash line in the unlocked and actuated position with both inner and outer handle operated components in their actuated position to permit door opening;

FIG. 15 is a vertical sectional view taken generally along the line 15—15 of FIG. 14;

FIG. 16 is a sectional view, taken generally along line 16—16 in FIG. 17 through the plate portion and slide with the lever and pivot shown in solid lines in edge view

and corresponding to FIG. 14 but with many details omitted for clarity, with the component parts shown in solid line in the locked and unactuated position with the outside handle in the relaxed or unactuated position and with the key actuated locking link locked or actuated and is shown in dot-dash lines in the locked and actuated position with the outside handle in the actuated position;

FIG. 17 is a vertical sectional view taken generally along the line 17—17 of FIG. 16 with the inside handle controlled linkage in unactuated position in solid line and in dot-dash line in locking position;

FIG. 18 is a sectional view, taken generally along line 18—18 of FIG. 19 through the plate portion but with the lever, pivot and slide shown in edge view in solid lines, corresponding to FIG. 14 but with many details omitted for clarity, with the component parts in an intermediate position during the rotor delocking action shown in solid line position when the outside handle is held in actuated position during door closing and shown in dot-dash line position when the outside handle remains in non-actuated position during door closing;

FIG. 19 is a vertical sectional view taken generally along the line 19—19 of FIG. 18 in the same manner as FIG. 17 but showing the control lever in the solid line, neutral, and unactuated position corresponding with both solid and dash line positions of FIG. 18;

FIG. 20 is a sectional view taken through the linkage along line 20—20 of FIG. 18;

FIG. 21 is a longitudinal sectional view of a lever taken along line 21—21 of FIG. 18;

FIG. 22 is a side view taken along the line 22—22 of FIG. 14;

FIG. 23 is a vertical sectional view taken along the line 23—23 in FIG. 24 of the lock in FIG. 14;

FIG. 24 is a vertical sectional view taken along the line 24—24 of FIG. 23;

FIG. 25 is a sectional view of a simplified form of the lock in FIG. 14, door, key cylinder, and connection there-

between taken generally along the lines 25—25 in FIG. 1 with the lock in FIG. 13 substituted therein with the component parts shown in key cylinder unlocked and locked actuated positions in solid lines and in dot-dash lines;

FIG. 26 is a sectional view, similar to FIG. 25, but showing the component parts in key cylinder locked and unlocked actuated positions with these positions shown in solid lines and in dot-dash lines;

FIG. 27 is a sectional view taken along the line 27—27 of FIG. 26 showing a portion of the key cylinder actuated mechanism in locked and in unlocked positions with these positions shown in solid and dot-dash lines, and showing the actuating lug of the mechanism in its unactuated, neutral or intermediate vertical position in dotted lines;

FIG. 28 is a sectional view of a third form of lock in the unlocked and unactuated position disclosing parts of the 200 reference number series adapted to be substituted for correspondingly numbered parts of the 100 reference numeral series in the second form of lock in FIG. 15;

FIG. 29 is a view taken along the line 29—29 of FIG. 28 and corresponding to the right hand portion of FIG. 14 of the second lock form;

FIG. 30, located to the left of FIG. 1, is an enlarged schematic view of a portion of FIG. 1 with a fourth form of the lock substituted therein;

FIG. 31 is a plan view of the rotor face of the lock in FIG. 30 with the component parts thereof shown in solid line in their unlocked and unactuated position with the door handles relaxed and with a key actuated locking link in unlocking position and with the component parts shown in dot-dash line in the unlocked and actuated position with both inner and outer handle operated components in their actuated position to permit door opening;

FIG. 32 is a vertical sectional view taken generally along the line 32—32 of FIG. 31;

FIG. 33 is a plan view, corresponding to FIG. 31, but with the lever and link, shown in FIG. 34, omitted for clarity and with the component parts shown in solid line in the locked and unactuated position with the outside handle in the relaxed or unactuated position and with the key actuated locking link locked or actuated and is shown in dot-dash lines in the locked and actuated position with the outside handle in the actuated position;

FIG. 34 is a vertical sectional view taken generally along the line 34—34 of FIG. 33 with the inside handle controlled linkage in unactuated position in solid line and in dot-dash line in locking position;

FIG. 35 is a plan view, corresponding to FIG. 31, but with the lever and link, shown in FIG. 36, omitted for clarity and with the component parts in an intermediate position during the rotor delocking action shown in solid line position when the outside handle is held in actuated position during door closing and shown in dot-dash line position when the outside handle remains in non-actuated position during door closing;

FIG. 36 is a vertical sectional view taken generally along the line 36—36 of FIG. 35 showing the control lever in the solid line, neutral, and unactuated position corresponding with both solid and dash line positions of FIG. 35;

FIG. 37 is a vertical sectional view taken along the line 37—37 of FIG. 31;

FIG. 38 is a vertical sectional view taken along the line 38—38 of FIG. 37;

FIG. 39 is a longitudinal sectional view taken generally along the line 39—39 of FIG. 31 through a control link;

FIG. 40 is a horizontal sectional view taken generally along the line 40—40 of FIG. 31 with the striker omitted; while,

FIG. 41 is a longitudinal sectional view taken generally along line 41—41 of FIG. 31 through a toggle link.

Before the lock forms here illustrated are specifically described, it is to be understood that the invention here involved is not limited to the structural details or arrange-

ment of parts here shown since locks embodying the present invention may take various forms. It also is to be understood that the phraseology or terminology herein employed is for purposes of description and not of limitation since the scope of the present invention is denoted by the appended claims.

Those familiar with the state of the art will recognize that the present invention may be applied in many ways and different components thereof may be used in many types of locks, but it has been chosen to illustrate the same as a free-handle lock on an automobile door with an automatic rotor delocking action when the door is being closed.

STRUCTURE ASSOCIATED WITH ALL FORMS OF LOCKS

Four forms of locks are disclosed: (1) Lock 10 in FIGS. 1-12, (2) Lock 110 in FIGS. 13-24, (3) Lock 210 in FIGS. 28 and 29 comprising the lock in FIGS. 13-24 with the structure of FIGS. 28 and 29 substituted for a portion thereof, and (4) Lock 310 in FIGS. 30-41. Locks 10, 110 and 310 are shown respectively in FIGS. 1, 13 and 30 (FIGS. 13 and 30 being an enlarged portion of FIG. 1 with a different lock substituted therein) as secured to a front door 14 on a conventional car body 12 having front and rear doors 14 and 16.

Each lock has an identical inside handle 26 movable between inside handle actuated position IA to unlatch door 14 to permit door opening, unactuated position IUA to keep door 14 latched in closed position, and locking position IL; an outside handle 30 in FIGS. 1, 25 and 26 movable between outside handle actuated position OA to unlatch door 14 to permit door opening, and unactuated position OUA to keep door 14 latched in closed position; lock key cylinder 22 in FIGS. 1 and 25-27 movable between actuated or lock unlocking position UL in FIGS. 2, 14, 25 or 31 to unlock the door, unactuated or neutral position KN in FIG. 27 for key insertion or removal, and another actuated or lock locking position L in FIGS. 9, 16, 26, or 33 to lock the door; and connecting mechanism movable between corresponding positions.

Both handles 26 and 30 will permit the door to remain latched in door closed position when they are in the unactuated position, and either will permit unlatching of the lock as the handle is moved to the actuated position so that the door will be free to swing from the door closed to the door open position about hinges 14a mounting door 14 on car body 12.

Inside handle 26 is pivotable clockwise in FIG. 1 about its pivot 26b on door 14 from an unlatching or actuated position IA through a neutral or unactuated position IUA to a locked position IL so as to correspondingly actuate any of these locks, but here shown specifically in FIG. 1 as lock 10, by pushing its associated link 28 in FIGS. 1, 3, 15, 28, or 32 toward the left by arm 26c of handle 26 to which link 28 is pivotally connected. The compression spring 27, located in FIG. 1 between stop lugs 14b and 14c on front door 14, is adapted to have its left end in FIG. 1 to be engaged by an upwardly extending arm 26a on the inside handle 26 in the neutral position IUA and to be compressed as the handle 26 is swung clockwise to the locked position IL while it moves the left end of spring 27 away from lug 14b toward lug 14c. Hence, when handle 26 is manually moved to the locked position IL, spring 27 will push the handle 26 counterclockwise back to the neutral or unactuated position IUA when it is released.

Outside handle 30 (shown in FIGS. 1, 25 and 26) is swingable outwardly from the door in a clockwise direction in FIG. 25 about pivot 31b (located on arm 31 fixed to door 14) from a normal or unactuated solid line position OUA into an actuated, dot-dash line position OA, which position is determined by door handle portion 30a of door handle 30 engaging handle frame stop portion

14d of door 14 in FIG. 25, so as to control any of these locks by pulling the links 32 upwardly in FIG. 2, 14 or 31 from solid line unactuated position OUA to dot-dash line actuated position OA. This control is obtained by a bell crank 33 in FIG. 25 pivotally connected to arm 31 and link 32 by pivots 33a and 33b respectively. Arm 33c of bell crank 33 is adapted to be engaged and moved by a pin 34 secured to handle 30 so that handle movement clockwise from solid to dot-dash line positions will cause corresponding counterclockwise movement of crank 33 and lifting movement of link 32; then, handle 30 may be swung counterclockwise back to the solid line position without effecting the OA position of link 32. Here, this counterclockwise return swing is caused by torsion spring 35 in FIG. 25 wound around pivot 31b and having its ends engaging handle 30 and arm 31. A spring, disclosed in more detail hereinafter in each lock 10, 110, 210 or 310 independently returns link 32 from the actuated dot-dash line position OA to unactuated solid line position OUA in FIG. 25 at the appropriate time.

Lock key cylinder 22 of FIG. 1, illustrated in FIGS. 25-27 with lock 110 and secured to door 14, permits actuation of lock key link 24 of any lock, but here shown specifically as lock 110, by lock key cylinder tumbler actuated lug 22a so that any of these locks may be locked or unlocked by a key from the outside of the car. The key may turn the tumbler of lock key cylinder 22 about a longitudinal axis and the tumbler actuated lug 22a carried thereby through a 180 degree arc, as shown by the three positions K1, KN and K2 of lug 22a in FIG. 27 wherein position KN is the unactuated or neutral position and the other positions are the locking and unlocking positions. The lock key cylinder 22 is of usual construction so that the key can be inserted and removed therefrom only in the neutral position KN. Hence, the user inserts the key in position KN, turns it to position K1 or K2 so as to move the mechanism to unlocked or locked position, returns it to position KN while the mechanism remains in the selected position, and then removes the key. As the key is turned to move lug 22a from position KN to K1, bell crank 25, pivotally secured to door 14 by pivot 25a in FIG. 26, is swung counterclockwise to the solid line position K1 and link 24, pivotally secured thereto, is lifted to the solid line position K1 by bell crank 25 being moved downwardly to the solid line position K1 in FIG. 27 by lug 22a being rotated clockwise in slot 25a in bell crank 25. As the key is turned from unactuated or neutral position KN to position K2, bell crank 25 in FIG. 25 is swung clockwise to the solid line position and link 24 is lowered to the solid line position K2 in FIG. 25 by bell crank 25 being moved upwardly to the dot-dash line position K2 in FIG. 27 by lug 22a rotated counterclockwise in the slot 25a in the bell crank 25. However, it should be apparent that rotating the key back to neutral position KN from position K1 or K2 for key removal, does not move slot 25a and lever 25 away from the previously selected position K1 or K2. However, the vertical dimension of slot 25a does permit movement of slot 25a and lever 25, while lug 22a is in position KN, from position K1 or K2 in FIGS. 27 to position K2 or K1 respectively by lock 10, 110, 210, or 310 whenever desired, as will be brought out in more detail hereinafter, without movement of lug 22a from neutral position KN.

STRUCTURE OF LOCK IN FIGS. 1-12

In FIGS. 1-12, the different components of the lock 10 and striker 18 will be described in detail with respect to the unlocked position UL in FIGS. 2 to 8 inclusive. Here, striker 18 is secured in FIGS. 1 and 4 to the forward face of body post 12a in any suitable manner while lock 10 and all the component parts of lock 10 are carried by front door 14.

The lock 10 includes in FIGS. 2 and 3 a lock plate 40 having a rotor plate portion 40a and a remote plate

portion 40b integrally connected together, and generally right angularly oriented with respect to each other with each being generally planar in form.

Lock 10 has a portion, located to the left of plate portion 40a in FIG. 4, coacting with the striker 18 secured to the body post 12a of car body 12. A strap-like rotor housing 42 in FIG. 4 extends laterally from plate portion 40a through the rearward face of the door 14 and is secured thereto by rotor housing mounting tabs 42a in FIGS. 2 and 4 each extending through a slot in the plate portion 40a and welded or otherwise secured thereto. Rotor 20 is rotatably mounted in rotor housing 42 by a pin 44 secured in rotor 20 in FIG. 4 and having its head rotatably mounted in housing 42 while a rotor shaft extension 20a in FIG. 4, formed integral with rotor 20, is rotatably mounted in the plate portion 40a. Secured to the right-hand end of this rotor shaft extension 20a in FIG. 4 and keyed against rotation relative thereto is a ratchet 46 having the same number of teeth as on rotor 20. Although six teeth are shown in the drawings, any satisfactory workable number may be used. Rotor housing 42 has integrally formed therewith two parallel end tabs 42b in FIG. 5 bent toward plate portion 40a from the section of housing 42 extending parallel in FIG. 4 to the plate portion 40a. A wedge pin 48 in FIG. 5, extending generally parallel to the striker 18, is secured to rotor housing 42 by having its outer ends peened over the end tabs 42b. A wedge 50, telescoped over the wedge pin 48, is normally biased toward the right in FIG. 5 by the helical compression spring 52 located partially within a counterbore of wedge 50 and between the shoulder of the counterbore and the left-hand tab 42b in FIG. 5. Lock 10, and its component rotor 20, rotor housing 42 and wedge 50, are adapted to telescope over striker 18 when the door 14 moves into its closed position so as to hold the door in closed and latched position and are adapted to telescope off striker 18 when the door 14 is swung toward its open position about hinges 14a.

The lock 10 also has a plurality of operative parts located to the right of rotor plate portion 40a in FIG. 4. Locking lever 54 and pawl lever 56 in FIGS. 2 and 4 are pivotally mounted in FIGS. 2 and 4 on a common pivot 57 comprised of a stud 58 and sleeve 60. In FIG. 4, the left end of the stud 58 has an enlarged head located at the left of the plate portion 40a while the shank of the stud 58 extends through a hole in this plate portion. Sleeve 60 is telescoped over the shank of the stud from the right-hand end of the shank in FIG. 4 and through the mounting bores of the levers 54 and 56. The right-hand end of the sleeve 60 has a flange over which is upset the right-hand end of the shank of stud 58 to lock these levers to the plate 40 while permitting them to freely rotate about this pivot 57. A spiral spring 62 in FIGS. 2 and 4, secured at its inner end by two struck-up lugs 40d from plate portion 40a, engages at its outer end an arm 56a of pawl lever 56 to normally bias lever 56 clockwise in FIG. 2 about pivot 57 so that the pawl 56b of pawl lever 56 will be located between adjacent teeth of ratchet 46 in solid line, unactuated position UA of FIG. 2 so as to be maintained in latching engagement with this ratchet but is movable counterclockwise against the bias of spring 62 to the dot-dash line unlatching and actuated position A in FIG. 2. Rubber bumper 64 in FIGS. 2 and 3 encircles lug 40c integral with and struck up from plate portion 40b and is adapted to resiliently stop this clockwise movement before pawl 56b strikes bottom with a clicking sound between adjacent teeth of ratchet 46. Integral stop arm 56c of pawl lever 56 is adapted to engage this rubber bumper 64 so that the lock will be silent in operation and is adapted to travel in and along the length of slot 40m in plate portion 40b.

In this lock, position K1 in FIGS. 25-27 is the locked or actuated position and position K2 is the unlocked or unactuated position. Key link 24, pivotally connected to lever 54, is shown in FIG. 2 in its actuated unlocking

position K2 and is adapted to be moved upwardly by key actuated link 24, in the manner previously described, to actuated locking position K1, shown in solid lines in FIG. 9, with locking lever 54 swinging clockwise about pivot 57 from its unlocked position UL to locked position L. Toggle spring 66 is pivotally connected at opposite ends to plate portion 40a and locking lever 54 to maintain the lever 54 in either of these two positions L or UL by having the spring end connected to lever 54 swing over center with respect to pivot 57 and the other spring end. These two positions L and UL of lever 54 are determined by the engagement of the stop arm 54a of locking lever 54 with the opposite ends of slot 40n in plate portion 40b through which it travels. Another arm of locking lever 54 has a cam face 54b adapted to engage or disengage a tooth of ratchet 46 at suitable times in the lock operation.

Outside handle 30 through its link 32 in FIGS. 2, 25 and 26 controls some functions of the lock. Link 32 is shown in FIGS. 2, 25 and 26 in its solid line or unactuated position OUA, but as it moves upwardly to its dot-dash line or actuated position OA, it swings release lever 68, to which it is pivotally connected by rivet 69, clockwise about pivot 70 by which lever 68 is pivotally connected to plate portion 40a. As lever 68 swings clockwise in FIG. 2, the arcuate surface of its release cam 68a bears against the surface of pad 72a on release arm 72 to swing the release arm 72 counterclockwise about pivot 74 by which arm 72 is pivotally connected to plate portion 40a.

Suitable linkage operatively connects locking lever 54, pawl lever 56 and release arm 72 in FIG. 2. A rotor releasing toggle link 76 is pivotally connected at its right end by rivet 78 to pawl lever 56 in FIG. 2, a toggle link 80 is pivotally connected at its left end by rivet 82 to release arm 72, and a control link 84 is pivotally connected at its upper end by pivot 86 with locking lever 54. The links 76, 80 and 84 are interconnected remote from the previously described pivots by a pivot 88 extending from a link 84 through a slot 76a in toggle link 76 and pivotally connected to toggle link 80. The control link 84 and its pivots 86 and 88 are formed of a continuous length of rod or wire stock with bent over ends, as shown in FIG. 7, but may be alternatively formed as a strip type strap with rivet type pivots. The bent over end forming pivot 88 extends through slot 76a in toggle link 76 and through a hole in toggle link 80 to be peened on the right-hand side thereof in FIG. 7. Pivot 86 is formed by having the bent over end of the wire forming control link 84 extend through a hole in locking lever 54 while a C-washer, clamping ring or snap ring 90 is snapped into a groove in control link 84 on the right-hand side of locking lever 54.

Also, lock 10 has parts actuated by inside handle 26 through link 28 in FIGS. 1 and 3. Remote control link 28 is pivotally connected at its left end in FIG. 3 to remote lever 94 by rivet 95 and lever 94 is pivotally connected by rivet 96 to remote plate portion 40b. As the inside front door handle 26 swings clockwise in FIG. 1, it moves link 28 toward the left in FIG. 3 and swings remote lever 94 counterclockwise in FIG. 3 about pivot 96 from an actuated or door unlatched position IA to a neutral, latched, or unactuated position IUA and then to a locked position IL.

Lever 94 has integral arms 94a and 94b. Arm 94a is adapted to move stop arms 54a and 56c from the bottom to the top of their slots 40n and 40m as lever 94 swings clockwise from locked position IL through neutral position IUA to actuated position IA so as to push arm 54a from locked position L to unlocked position UL and to push arm 56c from unactuated position UA to actuated position A. Arm 94b is adapted to push stop arm 54a from the unlocked position UL in FIGS. 2 and 3 at the top of slot 40n to the locked position L in FIGS. 9 and 10 at the bottom of slot 40n as lever 94 swings counter-

clockwise from unactuated position IUA to locked position IL.

MODE OF OPERATION OF LOCK IN FIGS. 1-12.

The operation of this lock and door will now be described in detail.

In FIGS. 1-8, the door 14 is shown in its closed position with the lock 10 in its unlocked position UL and latched or unactuated position UA and with the inner and outer door handles 26 and 30 in their unactuated positions IUA and OUA in the solid line with stop arms 54a and 56c limit stopped against the upper end of slot 40n and the lower end of slot 40m respectively in FIG. 3. Then, door 14 is kept in its closed position and prevented from swinging on hinges 14a outwardly to the open position by the pawl lever 56 being urged clockwise about pivot 57 in FIG. 2 into its solid line, unactuated position UA by the spring 62 to keep pawl 56b in latching position between adjacent teeth of ratchet 46 with pawl face 56r latched against one of the teeth. Since swinging of door 14 to its open position requires rotor housing 42 in FIG. 5 to move toward the left relative to the relatively stationary striker 18, any opening movement will tend to rotate rotor 20 clockwise in FIG. 5 and to rotate ratchet 46 clockwise in FIG. 2. Integral pawl face 56r of pawl 56b on pawl lever 56 engages in unactuated position UA with the side of a tooth on ratchet 46 to prevent this clockwise rotation of ratchet 46 to keep the door in its closed position since spring 62 urges pawl lever 56 clockwise into this latching position.

Door 14 may be easily opened and swung from the door closed to the door open position. One need merely move either the inside or outside handle 26 or 30 from its unactuated position IUA or OUA to actuated position IA or OA so as to swing pawl lever 56 counterclockwise about pivot 57 in FIG. 2 and to move pawl 56b and the other component parts from their solid line, latched, unactuated positions UA in FIG. 2 to their actuated or unlatched dot-dash line positions A in FIGS. 2 and 3. Inside handle 26 is swung counterclockwise in FIG. 1, link 28 is pulled toward the right from the solid line unactuated position IUA to the dot-dash line actuated positions IA in FIG. 3 so that lever arm 94a is swung clockwise in FIG. 3 from the solid line position to the dot-dash line position to engage stop arm 56c and swing pawl lever 56 counterclockwise in FIG. 2 about pivot 57 to swing pawl 56b and its pawl face 56r outwardly to the dot-dash line position to travel from the latched or unactuated position UA to the unlatched or actuated position A and stop arm 56c limit stops against the upper end of slot 40m in FIG. 3. If stop arm 54a has been in the locked position L at the lower end of slot 40n in FIG. 3, arm 94a will carry it to the unlocked position UL at the upper end of slot 40n. Then, ratchet 46 is free to rotate so that rotor 20 in FIG. 5 may rotate clockwise and will be permitted to move toward the left in FIG. 5 so that the door 14 may be swung to its open position. If the lock 10 is to be unlatched by the outside handle 30, one must swing outside handle 30 outwardly in FIGS. 1 and 25 from its unactuated position OUA to its actuated position OA to move link 32 upwardly from the solid to dot-dash line position in FIGS. 2, 25 and 26 to swing release lever 68 in FIG. 2 clockwise about pivot 70 so that release cam 68a will push pad 42a toward the right to FIG. 2, release arm 72 will swing counterclockwise about pivot 74, and toggle link 80 will push toggle link 76 toward the right in FIG. 2 by pivot 88 engaging the right end of slot 76a to swing pawl lever 56 counterclockwise about pivot 57 against the bias of spring 62 so as to swing pawl 56b and its pawl face 56r from the latched, unactuated position UA to the unlatched, actuated position A and thus move all of these parts from solid line position UA to dot-dash line position A in FIG. 2 so that ratchet 46 is

free to rotate and the door will open in the same manner. After the door has swung outwardly to its open position, it may be swung or slammed closed without touching either the inside or outside handle 26 or 30. After the door has opened and the door opening handle 26 or 30 has been released, cam 56b will be biased clockwise in FIG. 2 from the dot-dash line actuated position A to the solid line unactuated position UA by spring 62 so as to move from the unlatched to the latched position. When the door 14 is swung from its open to its closed position, the lock and its rotor body 42 will move toward the right in FIG. 5 relative to the relatively stationary striker 18 so that the travel of rotor 20 under the striker 18 will cause the rotor 20 to rotate counterclockwise as the door moves toward its closed position. As rotor 20 rotates counterclockwise, ratchet 46 in FIG. 2 rotates counterclockwise so that the teeth thereof successively force the pawl lever 56 to oscillate about pivot 57 by their individual engagements with the pawl face 56s of the pawl 56b until the door is fully closed. Then, spring 62 again biases the pawl lever 56 clockwise until pawl 56b is firmly seated in its latching or unactuated position UA between adjacent teeth of ratchet 46 with pawl face 56r latched firmly against a ratchet tooth. Note that slot 76a merely reciprocates back and forth over pivot 88 so that release arm 72 and outside handle 30 are not moved out of unactuated position OUA by the door closing action.

When the number and design of teeth in rotor 20 is so chosen that it is desirable to exert an upward force in FIG. 5 on the lock and rotor housing 42 to properly seat the rotor 20 against the striker, wedge 50 with its compression spring 52 is preferably used. Then, as the rotor housing 42 telescopes over the relatively stationary striker 18 in FIG. 5, beveled surface 18a of the striker 18 in FIG. 5 will coat with beveled surface 50a of the wedge 50 to wedge the lock and rotor housing 42 upwardly as the door moves toward its fully closed position against the compression of spring 52 so that the proper coaction will take place between the teeth of striker 18 and rotor 20 so that no vertical motion of the door will be allowable.

The lock 10 may be moved to its locked position L in FIG. 9 by inside handle 26. When inside handle 26 is in its neutral, unactuated and unlocked position IUA, remote lever 94 is in the solid line position of FIG. 10. As inside handle 26 is swung clockwise in FIG. 1 to the locked position IL, remote control link 28 is moved toward the left in FIG. 1 and remote control lever 94 is swung counterclockwise in FIG. 3 from the solid line unactuated position IUA to dot-dash line locked position IL so that arm 94b moves stop arm 54a from the upper end of slot 40n down against the lower end of slot 40n from the solid line unlocked position UL in FIGS. 2 and 3 to the solid line locked position L in FIGS. 9 and 10 to swing locking lever 54 clockwise from the solid line position UL in FIG. 2 to the solid line position L in FIG. 9 to pull toggle links 76 and 80 to the solid line position in FIG. 9 by control link 84. Locking lever 54 is movable between positions UL and L without key actuated movement of the tumblers of lock key cylinder 22 because (1) lug 22a is in the neutral or unactuated position KN in FIG. 27 since the key has returned it to this position prior to key removal from lock key cylinder 22, and (2) the vertical size of slot 25a in FIG. 27 permits bell crank 25 to move from unlocked position K2 to locked position K1 without movement of lug 22a from neutral or unactuated position KN and without key actuation of the tumblers of lock key cylinder 22. Now, the lock is in the locked position L and it is impossible to unlatch the lock and open the door by the outside handle 30. If the outside handle 30 is swung outwardly in FIGS. 1 and 25 from its unactuated position OUA to its actuated position OA so as to move outside handle link 32 upwardly from the

solid line to the dot-dash line position in FIGS. 9 and 25, pivot 88 in FIG. 9 will merely travel between the solid line and dot-dash line position in slot 76a but will not cause disengagement of pawl 56b from between the teeth of ratchet 46 so as to move it from the latched or unactuated position UA to the unlatched or actuated position A to permit door opening. After inside handle 26 has been manually actuated to move lever 94 from solid line position IUA to dot-dash line position IL in FIG. 10 to lock the door and then inside handle 26 is released, spring 27 in FIG. 1, pushing against arm 26a, will return handle 26 in a counterclockwise direction to the neutral position IUA and lever 94 to its solid line neutral position IUA in FIG. 10. This construction also prevents unauthorized entry of the automobile by an intruder through the unlocked door if the car occupant quickly manipulates the inside handle 26. The occupant may be safe even if the intruder has had time to move the outside handle 30 to the fully actuated position OA, has withdrawn pawl 56b from the latching or unactuated position UA between adjacent teeth of ratchet 46 to unlatching or actuated position A, and the rotor 20 has rotated $\frac{1}{6}$ of a rotation clockwise in FIG. 5 to partially open the door to the safety position with the rotor 20 held between the first and second tooth from the left in FIG. 5 on striker 18. If the occupant grabs the inside handle 26 and swings it clockwise in FIG. 1 to the locked position IL before rotor 20 has left the safety position, this movement of handle 26 will swing lever 94 counterclockwise to the dot-dash line position IL in FIG. 10 to lock the door by swinging locking lever 54 from unlocked position UL in FIG. 2 to locked position L in FIG. 9. This movement of lever 54 causes control link 84 to raise pivot 88 to break the toggle formed by the toggle links 76 and 80 by moving them to the solid line position of FIG. 9 so as to break the operative connection formed by the rigid toggle links 76 and 80 in FIG. 2 between outside handle 30 and latching pawl 56b. Then, spring 62 will rotate pawl lever 56 clockwise to the solid line or unactuated position UA in FIG. 9 to snap its pawl face 56r into latching engagement between adjacent teeth of and with a tooth of ratchet 46. This locking action will automatically take place independently of the position of outside handle 30; and once the door is locked, the outside handle 30 may be freely moved between unactuated and actuated positions OUA and OA without opening the door. Note that the car occupant can hold the door closed and lock the door by grasping only one inside handle 26, by both hands if necessary; and need not hold the door closed by grasping the handle with one hand while trying to actuate a separate inside lock button with the other. In lock 10, the door may also be locked from outside the automobile by the use of a key in the lock key cylinder 22. When the proper key is inserted in the lock 22 in FIGS. 1, 25 and 26 and is rotated clockwise in FIG. 27, the tumbler actuated lug 22a of the lock cylinder 22 will rotate clockwise in FIG. 27 from position KN to position K1 to lift link 24 from the unlocked, dot-dash line position K2 in FIG. 26 to the actuated, locking, solid line position K1 in FIG. 26 to move the component parts of the lock from the solid line, unlocked position UL in FIG. 2 to the solid line, locked position L in FIG. 9 to lock the door. Then, pivot 88 will be pulled upwardly by control link 84 and will raise toggle links 76 and 80 to the solid line position in FIG. 9 to provide the same locking action as mentioned in regard to inside handle 26. The door may be unlocked by key or by manual actuation of inside lever 26. If the key is inserted into lock 22 and is turned counterclockwise in FIG. 27 from neutral position KN to unlocked position K2, link 24 is forced downwardly from the locked, dot-dash line position K1 in FIG. 25 and locked solid line position L in FIG. 9 to the actuated unlocking solid line position UL in FIG.

2 and position K2 in FIG. 25. If inside handle 26 is swung counterclockwise in FIG. 1 from unactuated position IUA to actuated position IA, it swings lever 94 clockwise from the solid line position IUA in FIG. 10 toward the dot-dash line position IA of FIG. 3 to move arm 54a between the positions L and UL in these drawing figures.

Also, if outside handle 30 is jammed by a crash or for any other reason in actuated position OA, unactuated position OUA, or any intermediate position, while locked or unlocked, the car occupant will still be able to open the door, although the door will not automatically open as the result of any such jamming of the outside handle. Pawl 56b may be unlatched at any time by moving inside handle 26 counterclockwise in FIG. 1 to the actuated position IA, and this motion will move lever 54 to unlocked position UL, if it is in locked position L, and will move pawl 56b to its unlatched or actuated position A independently of the location of outside handle 30.

Lock 10 has automatic delocking. If the door 14 is swung to its open position, locked by either inside handle 26 or by key actuation of lock key cylinder 22, and then the door 14 is swung to its closed position without touching either handle 26 or 30, the lock 10 will operate properly, the lock 10 will be in unlocked position UL when closed, and the door can be then opened by outside handle 30. This locking action will move the lock parts to the solid line, locked position L of FIG. 9 in the manner previously described. Swinging the door to its closed position will automatically delock rotor 20 of the lock 10 and move the parts to the solid line, unlocked position UL of FIG. 2. As the door 14 moves toward the closed position, the lock and its rotor housing 42 in FIG. 5 will move toward the right relative to relatively stationary striker 18 so that rotor 20 rotates counterclockwise and this causes ratchet 46 to rotate counterclockwise in FIGS. 2 and 9 so that the component lock parts move from the solid line position in FIG. 9 through the dot-dash line position in FIG. 11 to the solid line positions in FIG. 2. Counterclockwise rotation of ratchet 46 performs two functions. First, cam face 54b, providing a small lever arm about pivot 57, is forced, by the immediately clockwise located tooth profile of ratchet 46, upwardly in FIGS. 9 and 11 to rotate locking lever 54 in a counterclockwise direction from the solid line, locked position L in FIG. 9 through the solid line position in FIG. 11 to the solid line, unlocked position UL in FIG. 2 to automatically unlock the lock by pushing pivot 88 downwardly to straighten the toggle formed by links 76 and 80 by moving them between the solid line positions of FIGS. 9 and 2. Locking lever 54 is movable between positions L and UL without key actuated movement of the tumblers of lock key cylinder 22 because (1) lug 22a is in the neutral or unactuated position KN in FIG. 27 since the key has returned it to this position prior to key removal from lock key cylinder 22, and (2) the vertical size of slot 25a in FIG. 27 permits bell crank 25 to move from locked position K1 to unlocked position K2 without movement of lug 22a from neutral or unactuated position KN and without key actuation of the tumblers of lock key cylinder 22. Second, counterclockwise rotation of ratchet 46 causes the immediately clockwise located tooth profile of the ratchet to act against pawl face 56s of pawl 56b to swing pawl lever 56 about pivot 57 in a counterclockwise direction against the resilient bias of spring 62 from its unactuated, latching position UA toward its actuated, unlatching position A so that rotor 20 may rotate properly and let the door move fully to its closed position at which time spring 62 returns pawl lever 56 in a clockwise direction to urge the pawl 56b inwardly between adjacent teeth of ratchet 46 to latched or unactuated position UA. Now, actuation of outer handle 30 will open the door since unlocking has occurred.

If the door 14 is open, the door is locked and the outside handle 30 is swung to its actuated position OA, as shown by the dot-dash lines in FIG. 9, the lock 10 will

still properly operate when the door is slammed to its closed position while the outside handle 30 is held in its actuated position OA and the unlocked door then can be opened from the outside by handle 30. As the door moves toward its closed position, the lock parts are in the dot-dash line or actuated position OA of FIG. 9 with pivot 88 near the right end of slot 76a in FIG. 9 but not against it. As the counterclockwise rotation of the ratchet 46 causes the parts to move through the solid line position of FIG. 11, the outside handle 30 will remain substantially in its actuated position OA because of the design of links 76, 80 and 84. If there is any tendency to urge release arm 72 in the clockwise direction in FIG. 9 or 11 to move the outside handle 30 back toward its unactuated position OUA, there will be sufficient give in spring 62 to permit the outside handle 30, if sufficient pressure is applied thereto, to remain in its actuated position OA. Also, as the parts approach the dot-dash line or actuated position OA in FIG. 2, the pivot 88 should preferably engage against the right end of slot 76a so as to forcefully move pawl lever 56 counterclockwise about pivot 57 against the bias of spring 62 to swing the pawl 56b outwardly toward its actuated or unlatched position A beyond the outer edge of the teeth of ratchet 46 because the ratchet 46 should be preferably in a free wheeling position when the door is in unlocked position UL and the outside handle 30 is in its actuated position OA in the manner shown by dot-dash lines in FIG. 2 so that the door will easily open when the outside handle 30 is actuated. Also, cam face 54b is forced out by a tooth profile on ratchet 46 to rotate the locking lever 54 counterclockwise to unlock the lock by swinging lever 54 to unlocked position UL to push pivot 88 downwardly by control link 84. Hence, the lock 10 will be automatically moved to unlocked position UL as the door closes by moving the lock parts from the locked position L of FIG. 9 to the unlocked position UL of FIG. 2 through the FIG. 11 position whether the outside handle 30 is in actuated position OA, unactuated position OUA, or an intermediate position, and the lock 10 may be unlatched by actuating outside handle 30 to move pawl 56b to an actuated and unlatched position A.

The door may also be easily locked from the outside by inserting the proper key in cylinder lock 22 after the door has been moved to its fully closed position. Then, rotation of the key clockwise in FIG. 27 will move lug 22a from position KN to position K1 to cause the parts to assume the locked position K1 in FIGS. 25 and 26 and the locked position L in FIG. 9. Then, the outside handle 30 is free to move between its positions OA and OUA or may have an idling action, and this movement will not unlatch the door as the operator moves it between unactuated position OUA and actuated position OA. During this movement, release arm 72 oscillates around pivot 74 so that release lever link 80 moves pivot 88 back and forth along the length of slot 76a. However, this lost movement of pivot 88 in slot 76a should preferably be restricted by a suitable end stop, formed by engagement of stop portions 14d and 30a in FIG. 25, limiting the movement of outside handle 30 and link 32 within a desirable range. For example, it is preferred that when the outside handle 30 is in its actuated position OA, as shown in dot-dash lines in FIG. 9, and these stop portions 14d and 30a are engaging, a gap 76b will still remain between pivot 88 and the right-hand end of slot 76a so that anyone attempting to unlock the door will not be able to begin to move pawl 56b even slightly out of its fully latched or unactuated position UA shown in FIG. 9.

Since this gap 76b exists, it should also be apparent that when the door is locked, with the parts in the solid line position of FIG. 9, the outside handle 30 may be moved between actuated and unactuated positions OA and OUA, shown by dot-dash and solid line positions in FIG. 9, without causing damage to the lock components.

In lock 10, it should be noted that the construction and

coaction of control link 84 coacting with slot 76a and toggle links 76 and 80 controls the delocking and locking action, controls the toggle action, prevents the toggle from swinging over center in the downward direction, prevents unauthorized unlatching movement of pawl 56b from unactuated position UA by actuation of outside handle 30 after the door is closed and locked, permits door slamming without disturbing the outside handle 30 in the unactuated position OUA, enables the occupant to prevent the entry of intruders, permits the door to be opened from the inside by movement of inside handle 26 to actuated position IA even when the outside handle 30 is jammed in any position, and permits the lock to have all desirable operating characteristics.

Now it should be apparent that in FIGS. 1-12 there has been disclosed a lock or latch mechanism 10 having latch means including rotor 20 for latching cooperation with keeper means or striker 18, detent means or pawl lever 56 pivotally mounted on an axis formed by pivot 57 and cooperable with the ratchet 46 of the latch means for releasably detaining such latch means in latching cooperation with the keeper means, manually operable control means including outside handle link 32, means, including links 76, 84 and 88, operatively connecting said control means with said detent means and movable into one position shown as unlocked position UL for release actuation of said detent means upon manual operation of said control means with consequent release of said latch means and into another position shown as locked position L for preventing said release actuation by said manual operation, and a lever 54 pivotally connected on the axis formed by pivot 57 and responsive to relative movement between said latch means and keeper means during door closing for automatically moving said connecting means from said other position L to said one position UL. Also, the axis of said detent means and the axis of said lever are coaxial on pivot 57, ratchet 46 of said latch means has a plurality of circumferentially arranged teeth, said detent means has a pawl portion 56b engageable with said latch means between a pair of adjacent teeth, and said lever 54 has a cam face portion 54b engageable with said latch means between a different pair of adjacent teeth in FIG. 9.

STRUCTURE OF LOCK IN FIGS. 13-24

The different components of the lock 110 and striker 118 will be described in detail with respect to the unlocked position UL in FIGS. 14, 15, 22, 23 and 24. Here, striker 118 in FIGS. 22, 23 and 24 is adapted to be secured to the forward face of body post 12a in any suitable manner, such as striker 18 is secured in FIGS. 1 and 4, while lock 110 and all the component parts of lock 110 are carried by front door 14.

Lock 110 includes in FIGS. 14, 15, 23 and 24 a base frame including a lock plate 140 having a rotor plate portion 140a and a remote plate portion 140b integrally connected together, and generally right angularly oriented with respect to each other with each being generally planar in form. A door lock cover 141 (having some portions shown in solid line in FIG. 14 and other portions cut away with the remaining plate outline shown in dot-dash lines), extending parallel to plate portion 140a, has integrally formed therewith at its lower left end in FIG. 14 a strap portion 141a in FIGS. 14 and 23 extending at right angles to cover 141 and portion 140a and having a shoulder abutting against portion 140a to space apart portion 140a and cover 141; a mounting tab 141b extending from this shoulder, through a slot in portion 140a, and bent at right angles to strap portion 141a to keep the shoulder against portion 140a; and a shoulder formed at the lower right end of cover 141 in FIG. 14 bearing against remote plate portion 140b with a mounting tab 141c in FIGS. 14, 15 and 24 extending from this shoulder, through a slot in portion 140b and bent at right angles to cover 141 to keep the shoulder against portion 140b. Plate portion 140a has an aperture 140r in FIGS. 14, 23 and 24 having its

upper portion covered by door lock cam stud plate 143 in FIGS. 14, 23 and 24 welded to portion 140a around the edges thereof. A strap-like strike plate and rotor housing 142 in FIGS. 22, 23 and 24 extends laterally from plate portion 140a through the rearward face of the door 14 and is secured to portion 140a by lower rotor housing mounting tab 142a extending through the lower portion of aperture 140r and welded to the face of portion 140a remote from housing 142 and by upper rotor housing mounting tab 142b located within a struck up recess 140p in plate portion 140a in FIGS. 23 and 24 closed by plate 143 with tab 142b sandwiched between and welded to both plate 143 and portion 140a. Plate 143 has an arcuate lower edge forming with the lower portion of aperture 140r and the top of tab 142a a circular aperture 140s in FIGS. 14, 23 and 24.

Lock 110 has a portion, located to the right of plate portion 140a in FIG. 23, coacting with the striker 118 secured to the body post 12a of car body 12. This includes strap-like rotor housing 142 in FIGS. 22, 23 and 24 and rotor 120 rotatably mounted in rotor housing 142 on a sleeve 145 secured to rotor housing 142 and to door lock cover 141 by a door lock rotor stud 144 having a head at its right end in FIG. 23, telescoped within sleeve 145 upon which rotor 120 is rotatably mounted, and having its left end in FIG. 23 peened over upon a flange of sleeve 145. Integrally formed with rotor 120 for rotation therewith and axially spaced therefrom is a ratchet 146 in FIGS. 14 and 23 having the same number of teeth as rotor 120 and a circular flange 120b located axially therebetween and rotatable within a circular aperture 140s. Although four teeth are shown in the drawings on rotor 120 and ratchet 146, any satisfactory workable number may be used. Hence, lock 110 and its component rotor 120, and rotor housing 142 are adapted to telescope over stationary striker 118 when the door 14 moves into its closed position so as to hold the door in closed and latched position and are adapted to telescope off striker 118 when the door 14 is swung toward its open position about hinges 14a.

Lock 110 also has a plurality of operative parts located to the left of rotor plate portion 140a in FIG. 23, which parts are more clearly shown in FIGS. 14 and 15. Locking lever 154 and lifting cam lever 156 in FIG. 14 are pivotally mounted on pivots 159 and 157 respectively. Long cam 153 and short cam 155 are also pivotally mounted on pivot 157. Pivot 159 is a rivet rotatably mounting lever 154 to lower mounting tab 142a and plate portion 140a. Pivot 157 comprises a stud 158 and sleeve 160 in FIGS. 14 and 23. In FIG. 23, the right end of the stud 158 has an enlarged head located at the right of stud plate 143 while the shank of the stud 158 extends through a hole in this plate. Sleeve 160 is telescoped over the shank of the stud from the left-hand end of the shank in FIG. 23 and through the mounting bores of the cams 153 and 155 and of the lever 156. The left-hand end of the sleeve 160 has a flange over which is upset the left-hand end of the shank of stud 158 to lock this lever and these cams to the plate 140 while permitting them to freely rotate about this pivot 157. Spiral springs 161, 162 and 163 in FIGS. 14 and 23, secured at their inner ends by two struck-up lugs 140d from plate portion 140a, respectively engage at their outer ends long cam 153, cam 156b of lifting cam lever 156 and short cam 155 to normally bias these cams and lever counterclockwise in FIG. 14 about pivot 157 so that the cams 153, 155 and 156b will be located between adjacent teeth of ratchet 146 in solid line, unactuated position UA of FIG. 14 so as to be maintained in latching engagement with this ratchet but are movable clockwise against the bias of springs 161, 162 and 163 to the dot-dash line, unlatching and actuated position A in FIG. 14 by keeper flange 156d of lever 156 as lever 156 is swung clockwise. Integral arm 156c of lifting cam lever 156 is adapted to travel during this movement through and along the length of

detent 140m formed by a struck-up portion in plate portion 140b, as seen in FIGS. 14, 15 and 24.

In lock 110, position K1 in FIGS. 25-27 is the locked or actuated position L and position K2 is the unlocked or actuated position UL. Key link 24, pivotally connected to lock slide 165, is shown in FIGS. 14 and 15 in its actuated unlocking position K2 and is adapted to be moved upwardly by key actuated link 24 in the manner previously described, to actuated locking position K1, shown in solid lines in FIG. 16, with lock slide 165 swinging locking lever 154 counterclockwise about pivot 159 from its unlocked position UL to locked position L. Lock slide 165 has an outwardly extending lug 165a fitting loosely into slot 154c of locking lever 154 in FIGS. 14 and 15 to convert the vertical reciprocation of slide 165 into oscillation of locking lever 154 about pivot 159 between unlocked position UL in FIGS. 14 and 15 and locked position L in FIGS. 16 and 17. Lock slide 165 is slidably secured to lock plate 140 for vertical movement in FIGS. 14 and 15 between these positions by parallel surfaces including a lug 165b of slide 165 riding on rotor plate portion 140a, bearing lug 165c of slide 165 riding against edge 140f of struck-up pad 140g struck-up from remote plate portion 140b, and surface 165d bearing against cover 141. Slide 165 is kept entrapped against the face of remote plate portion 140b in FIGS. 14 and 15 by lug 141d struck-up from cover 141 and by remote lever 194 pivotally connected to pad 140g by rivet 196. Locking position L and unlocking position UL are determined respectively by lug 165f of slide 165 engaging in FIG. 17 against edge 140h of struck-up pad 140g and by the end 154d of locking lever 154 engaging strap portion 141a in FIGS. 14 and 23 as an end stop. Toggle spring 166 in FIG. 15 is pivotally connected at opposite ends to plate portion 140b and lock slide 165 to maintain the slide 165 and lever 154 in either of these two positions by having the spring end connected to slide 165 swing over center with respect to the other spring end. Another arm of locking lever 154 has a cam face 154b in FIG. 16 adapted to engage or disengage a tooth of ratchet 146 at suitable times in the lock operation.

In lock 110, the outside handle 30 through its link 32 in FIGS. 14, 25 and 26 controls some functions of the lock. Link 32 is shown in FIGS. 14, 25 and 26 in its solid line or unactuated position OUA, but as it moves upwardly to its dot-dash line or actuated position OA, it swings release lever 172, to which it is pivotally connected by rivet 169, clockwise about rivet 174 by which lever 172 is pivotally connected to plate portion 140a.

A linkage operatively connects locking lever 154, lifting cam lever 156 and release arm 172 in FIGS. 14, 20 and 21. A rotor releasing toggle link 176 is pivotally connected at its right end by rivet 178 to lifting cam lever 156 in FIGS. 14 and 20, a toggle link 180 is pivotally connected at its left end by rivet 182 to release arm 172, and a control link 184 is pivotally connected at its lower end by pivot 186, formed by a rivet, with locking lever 154. The links 176, 180 and 184 are interconnected remote from the previously described pivots by a pivot 188 formed by a rivet pivotally connected to link 184, extending through a slot 176a in toggle link 176 and pivotally connected to toggle link 180. Control link 184 is shown as a strip type strap but may instead be formed of rod or wire stock, like link 84.

Lock 110 also has parts actuated by inside handle 26 through link 28 in FIGS. 13 and 15. Remote control link 28 is pivotally connected at its left end in FIG. 15 to remote lever 194 by rivet 195 and lever 194 is pivotally connected by rivet 196 to pad 140g on remote plate portion 140b. As the inside front door handle 26 swings clockwise in FIGS. 1 and 13, it moves link 28 toward the left in FIG. 15 and swings remote lever 194 clockwise in FIG. 15 about rivet 196 from an actuated or door unlatched position IA to a neutral, latched, or unactuated position IUA and then to a locked position IL.

Lever 194 has integral arm 194c. Arm 194c adapted to move downwardly lifting cam lever arm 156c and locking slide 165 from the locked and unactuated positions L and UA of FIG. 17 to the unlocked and actuated positions UL and A of FIG. 15 as lever 194 swings counterclockwise from locked position IL through neutral position IUA to actuated position IA so as to push lock slide 165, by engagement of arm 194c with lug 165g on slide 165, from locked position L to unlocked position UL and to push arm 156c from unactuated position UA to actuated position A.

MODE OF OPERATION OF LOCK IN FIGS. 13-24

The operation of this lock and door will now be described in detail.

FIGS. 13, 14 and 15 show the door 14 in its closed position with the lock 110 in its unlocked position UL and latched or unactuated position UA and with the inner and outer door handles 26 and 30 in their unactuated positions IUA and OUA in solid line. Then, door 14 is kept in its closed position and prevented from swinging on hinges 14a outwardly to the open position by the long cam 153, short cam 155 and lifting cam lever 156 being urged counterclockwise about pivot 157 in FIG. 14 into their solid line, unactuated position UA by the springs 161, 163 and 162 respectively to keep cams 153, 155 and 156b in latching position between adjacent teeth of ratchet 146 with cam faces 153r, 155r and 156r latched against one of the teeth. Since swinging of door 14 to its open position requires rotor housing 142 in FIG. 24 to move toward the right relative to the relatively stationary striker 118, any opening movement will tend to rotate rotor 120 counterclockwise in FIG. 24 and to rotate ratchet 146 clockwise in FIG. 14. Integral cam face 156r of cam 156b on lifting cam lever 156 and cam faces 153b and 155b of cams 153 and 155 engage in unactuated position UA with the side of a tooth on ratchet 146 to prevent this clockwise rotation of ratchet 146 to keep the door in its closed position since springs 161, 163 and 162 urge cams 153 and 155 and lifting cam lever 156 counterclockwise into this latching position.

One can easily open the door 14 and swing it from door closed to door open position. He need merely move either the inside or outside handle 26 or 30 from its unactuated position IUA or OUA to actuated position IA or OA so as to swing lever 156 clockwise about pivot 157 in FIG. 14 to swing clockwise cam 156b of lever 156 to swing clockwise cams 153 and 155 by keeper flange 156d of lever 156, and to move the other component parts from their solid line, latched, unactuated positions UA in FIG. 14 to their actuated or unlatched dot-dash line positions A in FIGS. 14 and 15. Inside handle 26 is swung counterclockwise in FIG. 1, link 28 is pulled toward the right from the solid line unactuated position IUA to the dot-dash line actuated position IA in FIG. 15 so that lever arm 194c is swung counterclockwise in FIG. 15 from the solid line position to the dot-dash line position to engage arm 156c and swing lifting cam lever 156 clockwise in FIG. 14 about pivot 157 to swing cams 153, 155 and 156 and their cam faces 153r, 155r and 156r outwardly to the dot-dash line position to travel from the latched or unactuated position UA to the unlatched or actuated position A. If lock slide lug 165g has been in the locked position L in FIG. 17, arm 194c will carry it downwardly to the unlocked position UL in FIG. 15. Then, ratchet 146 is free to rotate so that rotor 120 in FIG. 24 may rotate counterclockwise and will be permitted to move toward the right in FIG. 24 so that the door 14 may be swung to its open position. If the lock 110 is to be unlatched by the outside handle 30, one must swing outside handle 30 outwardly in FIG. 1 from its unactuated position OUA to its actuated position OA to move link 32 upwardly from the solid to dot-dash line position in FIG. 14 to swing release arm 172 clockwise about pivot 174.

so that toggle link 180 will push toggle link 176 toward the right in FIG. 14 by pivot 188 engaging the right end of slot 176a to swing not only lifting cam lever 156 but also cams 153 and 155, by keeper flange 156d engaging these cams, clockwise about pivot 157 against the bias of springs 161, 162 and 163 so as to swing cams 153, 155 and 156b and their cam faces 153r, 155r, and 156r from the latched, unactuated position UA to the unlatched, actuated position A and thus move all of these parts from solid line position UA to dot-dash line position A in FIG. 14 so that ratchet 146 is free to rotate and the door will open in the same manner.

In lock 110, after the door has swung outwardly to its open position, it may be swung or slammed closed without touching either the inside or outside handle 26 or 30. After the door has opened and the door opening handle 26 or 30 has been released, cams 153, 155 and 156b will be biased counterclockwise in FIG. 14 from the dot-dash line actuated position A to the solid line unactuated position UA by springs 161, 163 and 162 so as to move from the unlatched to the latched position. When the door 14 is swung from its open to its closed position, the lock and its rotor body 142 will move toward the left in FIG. 24 relative to the relatively stationary striker 118 so that the travel of rotor 120 under the striker 118 will cause the rotor 120 to rotate clockwise as the door moves toward its closed position. As rotor 120 rotates clockwise, ratchet 146 in FIG. 14 rotates counterclockwise so that the teeth thereof successively force cams 153, 155 and 156b to oscillate about pivot 157 by the individual teeth engagements with the cam face 153s, 155s and 156s of cams 153, 155 and 156b until the door is fully closed. Then, springs 161, 162 and 163 again bias the lifting cams 153, 156b and 155 counterclockwise until they are firmly seated in their latching or unactuated position UA between adjacent teeth of ratchet 146 and these cams individually take up the clearance by having their cam faces 153r, 155r and 156r latched firmly against a ratchet tooth. Note that slot 176a merely reciprocates back and forth over pivot 188 so that release arm 172 and outside handle 30 are not moved out of unactuated position OUA by the door closing action.

As the rotor housing 142 telescopes to the left over the relatively stationary striker 118 in FIG. 24, top surface 118b of the striker 118 in FIG. 24 will coat with rotor housing surfaces 142d so that the proper coaction will take place between the teeth of striker 118 and rotor 120 so that no vertical motion of the door will be allowable.

One may move lock 110 to its locked position L in FIGS. 16 and 17 by inside handle 26. When inside handle 26 is in its neutral, unactuated and unlocked position IUA, remote lever 194 is in the solid line position of FIG. 17. As inside handle 26 is swung clockwise in FIG. 1 to the locked position IL, remote control link 28 is moved toward the left in FIGS. 13 and 17 and remote control lever 194 is swung clockwise in FIG. 17 from the solid line unactuated position IUA to dot-dash line locked position IL so that arm 194c moves upwardly lock slide 165, by arm engagement with shoulder 165h of slide 165, from the solid line unlocked position UL in FIGS. 14 and 15 to the solid line locked position L in FIGS. 16 and 17 to swing locking lever 154 counterclockwise from the solid line position UL in FIG. 14 to the solid line position L in FIG. 16 to pull toggle links 176 and 180 to the solid line position in FIG. 16 by control link 184. Locking lever 154 is movable between positions UL and L without key actuated movement of the tumblers of lock key cylinder 22 because (1) lug 22a is in the neutral or unactuated position KN in FIG. 27 since the key has returned it to this position prior to key removal from lock key cylinder 22, and (2) the vertical size of slot 25a in FIG. 27 permits bell crank 25 to move from unlocked position K2 to locked position K1 without move-

ment of lug 22a from neutral or unactuated position KN and without key actuation of the tumblers of lock key cylinder 22. Now, the lock is in the locked position L and it is impossible to unlatch the lock and open the door by the outside handle 30. If the outside handle 30 is swung outwardly in FIGS. 1, 13 and 25 from its unactuated position OUA to its actuated position OA so as to move outside handle link 32 upwardly from the solid line to the dot-dash line position in FIG. 16, pivot 188 will merely travel between the solid line and dot-dash line position in FIG. 16 in slot 176a but will not cause disengagement of cams 153, 155 and 156b from between the teeth of ratchet 146 so as to move it from the latched or unactuated position UA to the unlatched or actuated position A to permit door opening. After inside handle 26 has been manually actuated to move lever 194 from solid line position IUA to dot-dash line position IL in FIG. 17 to lock the door and then inside handle 26 is released, spring 27 in FIG. 1, pushing against arm 26a, will return handle 26 in a counterclockwise direction to the neutral position IUA and lever 194 to its solid line neutral position IUA in FIG. 17.

Lock 110 also has features to prevent unauthorized entry of the automobile by an intruder through the unlocked door if the car occupant quickly manipulates the inside handle 26. The occupant may be safe even if the intruder has had time to move the outside handle 30 to the fully actuated position OA, has withdrawn cams 153, 155 and 156b from the latching or unactuated position UA between adjacent teeth of ratchet 146 to unlatching or actuated position A, and the rotor 120 has rotated $\frac{1}{4}$ of a rotation counterclockwise in FIG. 24 to partially open the door to the safety position with the rotor 120 held between the first and second teeth from the right in FIG. 24 on striker 118. If the occupant grabs the inside handle 26 and swings it clockwise in FIG. 1 to the locked position IL before rotor 120 has left the safety position, this movement of handle 26 will swing lever 194 clockwise to the dot-dash line position IL in FIG. 17 to lock the door by having arm 194c push upwardly lock slide 165 by arm engagement with shoulder 165h, and by swinging locking lever 154 from unlocked position UL in FIG. 14 to locked position L in FIG. 16. This movement of lever 154 causes control link 184 to lower pivot 188 to break the toggle formed by toggle links 176 and 180 by moving them to the solid line position of FIG. 16 so as to break the operative connection formed by the rigid toggle links 176 and 180 in FIG. 14 between outside handle 30 and latching cams 153, 155 and 156b. Then, springs 161, 163 and 162 will rotate lifting cams 153, 155 and 156b counterclockwise to the solid line or unactuated position UA in FIG. 16 to snap the faces 153r, 155r and 156r of these cams into latching engagement between adjacent teeth of and with a tooth of ratchet 146. This locking action will automatically take place independently of the position of outside handle 30; and once the door is locked, the outside handle 30 may be freely moved between unactuated and actuated positions OUA and OA without opening the door. Note that the car occupant can hold the door closed and lock the door by grasping only one inside handle 26, by both hands if necessary; and need not hold the door closed by grasping the handle with one hand while trying to actuate a separate inside lock button with the other.

Door 14 may also be locked from outside the automobile by the use of a key in the lock key cylinder 22. When the proper key is inserted in the lock 22 in FIGS. 25 and 26 and is rotated counterclockwise in FIGS. 1 and 13, the tumbler actuated lug 22a of the lock cylinder 22 will rotate clockwise in FIG. 27 from position KN to position K1 to lift link 24 from the unlocked, dot-dash line position K2 in FIG. 26 to the actuated locking, solid line position K1 in FIG. 26 to move the component parts of the lock from the solid line, unlocked position UL in FIG. 14 to the solid line, locked position L in FIG. 16 to lock the door. Then, pivot 188 will be pulled down-

wardly by control link 184 and will lower toggle links 176 and 180 to the solid line position in FIG. 16 to provide the same locking actuation as mentioned in regard to inside handle 26.

Also, the door may be unlocked by key or by manual actuation of inside lever 26. If the key is inserted into lock 22 and is turned counterclockwise in FIG. 27 from neutral position KN to unlocked position K2, link 24 is forced downwardly from the locked dot-dash line position K1 in FIG. 25 and locked solid line position L in FIG. 16 to the actuated unlocking solid line position UL in FIG. 14 and position K2 in FIG. 25. If inside handle 26 is swung counterclockwise in FIG. 1 from unactuated position IUA to actuated position IA, it swings lever 194 counterclockwise from the solid line position IUA in FIG. 17 toward the dot-dash line position IA of FIG. 15 to move lock slide 165 downwardly and lever 154 clockwise between the positions L and UL in these drawing figures by having lever arm 194c push downwardly on lock slide lug 165g.

If outside handle 30 is jammed by a crash or for any other reason in actuated position OA, unactuated position OUA or any intermediate position, whether locked or unlocked, the car occupant will still be able to open the door. Cams 153, 155 and 156b may be unlatched at any time by moving inside handle 26 counterclockwise in FIG. 1 to the actuated position IA, and this motion will move lever 154 to unlocked position UL, if it is in locked position L, and will move cams 153, 155 and 156b to unlatched or actuated position A independently of the location of outside handle 30 because counterclockwise moving arm 194c moves downwardly arm 156c and lug 165g.

Also, automatic delocking is a feature of lock 110. If the door 14 is swung to its open position, locked by either inside handle 26 or by key actuation of lock key cylinder 22, and then the door 14 is swung to its closed position without touching either handle 26 or 30, the lock 110 will operate properly, the lock 110 will be in unlocked position UL when closed, and the door can be then opened by outside handle 30. This locking action will move the lock parts to the solid line, locked position L of FIG. 16 in the manner previously described. Swinging the door to its closed position will automatically delock rotor 120 of the lock 110 and move the parts to the solid line, unlocked position UL of FIG. 14. As the door 14 moves toward the closed position, the lock and its rotor housing 142 in FIG. 24 will move toward the left relative to relatively stationary striker 118 so that rotor 120 rotates clockwise and this causes ratchet 146 to rotate counterclockwise in FIGS. 14 and 16 so that the component lock parts move from the solid line position in FIG. 16 through the dot-dash line position in FIG. 18 to the solid line positions in FIG. 14. Counterclockwise rotation of ratchet 146 performs two functions. First, cam face 154b, providing a lever arm about pivot 159, is forced, by the immediately clockwise located tooth profile of ratchet 146, in FIG. 16 to rotate locking lever 154 in a clockwise direction from the solid line, locked position L in FIG. 16 through the solid line position in FIG. 18 to the solid line, unlocked position UL in FIG. 14 to automatically unlock the lock by pushing pivot 188 upwardly to straighten the toggle formed by links 176 and 180 by moving them between the solid line positions of FIGS. 16 and 14. Locking lever 154 is movable between positions L and UL without key actuated movement of the tumblers of lock key cylinder 22 because (1) lug 22a is in the neutral or unactuated position KN in FIG. 27 since the key has returned it to this position prior to key removal from lock key cylinder 22, and (2) the vertical size of slot 25a in FIG. 27 permits bell crank 25 to move from locked position K1 to unlocked position K2 without movement of lug 22a from neutral or unactuated position KN and without key actuation of the tumblers of lock key cylinder 22.

Second, counterclockwise rotation of ratchet 146 causes the immediately clockwise located tooth profile of the ratchet to act against cam faces 153s, 155s and 156s of cams 153, 155 and 156b to swing these cams and lever 156 about pivot 157 in a clockwise direction against the resilient bias of springs 161, 162 and 163 from unactuated latching position UA toward actuated, unlatching position A so that rotor 120 may rotate properly and let the door move fully to its closed position at which time springs 161, 162 and 163 return cams 153, 156b and 155 in a counterclockwise direction to urge them inwardly between adjacent teeth of ratchet 146 to latched or unactuated position UA. Now, actuation of outer handle 30 will open the door since unlocking has occurred.

In lock 110, if the door 14 is opened, the door is locked and the outside handle 30 is swung to its actuated position OA, as shown by the dot-dash lines in FIG. 16, the lock 110 will still properly operate when the door is slammed to its closed position while the outside handle 30 is held in its actuated position OA and the unlocked door then can be opened from the outside by handle 30. As the door moves toward its closed position, the lock parts are in the dot-dash line or actuated position OA of FIG. 16 with pivot 188 near the right end of slot 176a in FIG. 16 but not against it. As the counterclockwise rotation of the ratchet 146 causes the parts to move through the solid line position of FIG. 18, the outside handle 30 will remain substantially in its actuated position OA because of the design of links 176, 180 and 184. If there is any tendency to urge release arm 172 in the counterclockwise direction in FIG. 16 or 18 to move the outside handle 30 back toward its unactuated position OUA, there will be sufficient give in springs 161, 162 and 163 to permit the outside handle 30, if sufficient pressure is applied thereto, to remain in its actuated position OA. Also, as the parts approach the dot-dash line or actuated position OA in FIG. 14, the pivot 188 should preferably engage against the right end of slot 176a so as to forcibly move lifting cam lever 156 clockwise about pivot 157 against the bias of spring 162 to swing the cams 151, 153 and 156b outwardly toward actuated or unlatched position A beyond the outer edge of the teeth of ratchet 146 because the ratchet 146 should be preferably in a free wheeling position when the door is in unlocked position UL and the outside handle 30 is in its actuated position OA in the manner shown by dot-dash lines in FIG. 14 so that the door will easily open when the outside handle 30 is actuated. Also, cam face 154b is forced out by a tooth profile on ratchet 146 to rotate the locking lever 154 clockwise to unlock the lock by swinging lever 154 to unlocked position UL to push pivot 188 upwardly by link 184. Hence, the lock 110 will be automatically moved to unlocked position UL as the door closes by moving the lock parts from the locked position L of FIG. 16 to the unlocked position UL of FIG. 14 through the FIG. 18 position whether the outside handle 30 is in actuated position OA, unactuated position OUA, or an intermediate position, and the lock 110 may be opened by actuating outside handle 30 to move lever 156 clockwise to carry cams 153, 155 and 156b to actuated and unlatched position A.

Also, the door may also be easily locked from the outside by inserting the proper key in cylinder lock 22 after the door has been moved to its fully closed position. Then, rotation of the key clockwise in FIG. 27 will move lug 22a from position KN to position K1 to cause the parts to assume the locked position K1 in FIGS. 25 and 26 and the locked position L in FIG. 16. Then, the outside handle 30 is free to move between its positions OA and OUA or may have an idling action, and this movement will not unlatch the door as the operator moves it between unactuated position OUA and actuated position OA. During this movement, release arm 172 oscillates around pivot 174 so that release lever link 180 moves pivot 188 back and forth along the length of slot 176a.

However, this lost motion movement of pivot 188 in slot 176a should preferably be restricted by a suitable end stop, formed by engagement of stop portions 14d and 30a in FIG. 25, limiting the movement of outside handle 30 and link 32 within a desirable range. For example, it is preferred that when the outside handle 30 is in its actuated position OA, as shown in dot-dash lines in FIG. 16, and these stop portions 14d and 30a are engaging, a gap 176b will still remain between pivot 188 and the right-hand end of slot 176a so that anyone attempting to unlock the door will not be able to begin to move lever 156 and cams 153, 155 and 156b even slightly out of fully latched or unactuated position UA shown in FIG. 16.

Because of gap 176b, it should also be apparent that when the door is locked, with the parts in the solid line position of FIG. 16, the outside handle 30 may be moved between actuated and unactuated positions OA and UOA, shown by dot-dash and solid line positions in FIG. 16, without causing damage to the lock components.

It should be noted that the construction and coaction of control link 184 coacting with slot 176a and toggle links 176 and 180 controls the delocking and locking action, controls the toggle action, prevents the toggle from swinging upwardly over center to an extent sufficient to collapse the toggle, prevents unauthorized unlatching movement of cams 153, 155 and 156b by lever 156 from unactuated position UA by actuation of outside handle 30 after the door is closed and locked, permits door slamming without disturbing the outside handle 30 in the unactuated position UOA, enables the occupant to prevent the entry of intruders, permits the door to be opened from the inside by movement of inside handle 26 to actuated position IA even when the outside handle 30 is jammed in any position, and permits the lock to have all desirable operation characteristics.

In FIGS. 13-24, there have been disclosed a lock or latch mechanism 110 having latch means including rotor 120 for latching cooperation with keeper means or striker 118, detent means or lever 156 pivotally mounted on an axis formed by pivot 157 and cooperable with the ratchet 146 of the latch means for releasably detaining such latch means in latching cooperation with the keeper means, manually operable control means including outside handle link 32, means, including links 176, 184 and 188, operatively connecting said control means with said detent means and movable into one position shown as unlocked position UL for release actuation of said detent means upon manual operation of said control means with consequent release of said latch means and into another position shown as locked position L for preventing said release actuation by said manual operation, and a lever pivotally connected on an axis formed by pivot 159 and responsive to relative movement between said latch means and keeper means during door closing for automatically moving said connecting means from said other position L to said one position UL.

The axis of said detent means formed by pivot 157 and the axis of said lever 154 formed by pivot 159 are spaced laterally apart in FIG. 14, a reciprocatable slide 165 is operatively connected to lever 154 for moving said lever between said positions L and UL, said slide 165 having a peripheral edge 165d with a lug 165g located thereon, another manually operable control means including a pivoted lever 194 for release actuation of said detent means or lever 156 and for engagement with said lug 165g to move said slide 165 from said other position L to said one position UL.

LOCK IN FIGS. 28 AND 29

The lock 210 in FIGS. 28 and 29 is constructed in basically the same way and operates in basically the same way as the lock 110 in FIGS. 13-24. The only changes include a different shaped remote plate portion 240b with pad 240g having edges 240f and 240h and with

detent 240m; a different shaped door lock slide 265 with lugs 265a, 265b, 265c, 265f, and 265g, with surface 265d and shoulder 265h; different shaped lever 294 with arm 294c; spring 266; and with a different shaped arm 256c 5 on the lifting cam lever 156 corresponding with and operating the same respectively as remote plate portion 140b with pad 140g having edges 140f and 140h and with detent 140m; door lock slide 165 with lugs 165a, 165b, 165c, 165f and 165g, with surface 165d and shoulder 165h; lever 194 with arm 194c; spring 166; and arm 156c on the lifting cam lever 156. Slide 265 in FIG. 28 differs from slide 165 by having a closed end slot 265s straddling cover 141 to serve as a guide for vertical reciprocation of slide 265 and straddling lever arm 256c 15 with lug 265g located on one edge of slot 265s; slide 165 in FIG. 15 has peripheral edge 165d bearing against cover 141 and having a lug 165g located on this peripheral edge 165d.

When the aforementioned parts from FIGS. 28 and 29 20 are substituted for the corresponding parts in FIGS. 13-24, there has been disclosed a lock or latch mechanism 210 having latch means including rotor 20 for latching cooperation with keeper means or striker 118, detent means or lever 156 pivotally mounted on an axis formed by pivot 25 157 and cooperable with the ratchet 146 of the latch means for releasably detaining such latch means in latching cooperation with the keeper means, manually operable control means including outside handle link 32, means, including links 176, 184 and 188, operatively connecting said control means with said detent means and movable into one position shown as unlocked position UL for release actuation of said detent means upon manual 30 operation of said control means with consequent release of said latch means and into another position shown as 35 locked position L for preventing said release actuation by said manual operation, and a lever pivotally connected on an axis formed by pivot 159 and responsive to relative movement between said latch means and keeper means during door closing for automatically moving said connecting means from said other position L to said one position UL. The axis of said detent means formed by pivot 157 and the axis of said lever 154 formed by pivot 159 are spaced laterally apart in FIG. 14, a reciprocatable slide 265 is operatively connected to said lever 154 in FIG. 29 for moving said lever between said positions L and UL, said slide 265 including a closed end slot 265s with a lug 265g on one edge of said slot, another manually operable control means including a pivoted lever 294 45 for release actuation of said detent means or lever 156 by engagement with its arm 256c and for engagement with said lug 265g to move said slide 265 from said other position L to said one position UL.

STRUCTURE OF LOCK IN FIGS. 30-41

Different components of the lock 310 and striker 318 55 will be described in detail with respect to the unlocked position UL in FIGS. 31, 32, and 37-41 inclusive. Here, striker 318 in FIGS. 30 and 37 is adapted to be secured to the forward face of body post 12a in any suitable manner, such as striker 18 is secured in FIGS. 1 and 4, while lock 310 and all the component parts of lock 310 are carried by front door 14.

In FIGS. 31 and 32, lock 310 includes a lock plate 340 having a rotor plate portion 340a and a remote plate portion 340b integrally connected together and generally right angularly oriented with respect to each other with each being generally planar in form.

In FIG. 37, lock 310 has a portion, located to the left of plate portion 340a, coacting with the striker 310 secured to the body post 12a of car body 12. A strap-like rotor 70 housing 342 in FIG. 37 extends laterally from plate portion 340a through the rearward face of the door 14 and is secured thereto by rotor housing mounting tabs 342a in FIGS. 31 and 37, each extending through a slot in the plate portion 340a and bent to secure the parts together.

Rotor 320 is rotatably mounted in rotor housing 342 by a pin 344 secured in rotor 320 in FIG. 37 and having its head rotatably mounted in housing 342 while rotor shaft extension 320a in FIG. 37, formed integral with rotor 320, is rotatably mounted in the plate portion 340a. Secured to the right-hand end of this rotor shaft extension 320a in FIG. 37 and keyed against rotation relative thereto is a ratchet 346 having the same number of teeth as on rotor 320. Although six teeth are shown in the drawings, any satisfactory workable number may be used. Rotor housing 342 has integrally formed therewith two parallel end tabs 342b in FIGS. 38 and 40 bent toward plate portion 340a from the section of housing 342 extending parallel in FIG. 37 to the plate portion 340a. A wedge pin 348 in FIG. 38, extending generally parallel to the striker 318, is secured to rotor housing 342 by having its outer ends peened over the end tabs 342b. A wedge 350, telescoped over the wedge pin 348, is normally biased toward the right in FIG. 38 by the helical compression spring 352 located partially within a counterbore of wedge 350 and between the shoulder of the counterbore and the left-hand tab 342b in FIGS. 38 and 40. Lock 310, and its component rotor 320, rotor housing 342 and wedge 350, are adapted to telescope over stationary striker 318 when the door 14 moves into its closed position so as to hold the door in closed and latched position and are adapted to telescope off striker 318 when the door 14 is swung toward its open position about hinges 14a.

Lock 310 also has a plurality of operative parts located to the right of rotor plate portion 340a in FIG. 37. Locking lever 354 and pawl lever 356 in FIGS. 31 and 37 are pivotally mounted in FIGS. 31 and 37 on a common pivot 357 comprised of a stud 358 and sleeve 360. In FIG. 37, the left end of the stud 358 has an enlarged head located at the left of the plate portion 340a while the shank of the stud 358 extends through a hole in this plate portion. Sleeve 360 is telescoped over the shank of the stud from the right-hand end of the shank in FIG. 37 and through the mounting bores of the levers 354 and 356. The right-hand end of the sleeve 360 has a flange over which is upset the right-hand end of the shank of stud 358 to lock these levers to the plate 340 while permitting them to freely rotate about this pivot 357. Spiral spring 362 in FIGS. 31 and 37, secured at its inner end by two struck-up lugs 340d from plate portion 340a, engages at its outer end an arm 356a of pawl lever 356 in FIG. 33 to normally bias lever 356 counterclockwise in FIG. 31 about pivot 357 so that the pawl 356b of pawl lever 356 will be located between adjacent teeth of ratchet 346 in solid line unactuated position UA of FIG. 31 so as to be maintained in latching engagement with this ratchet but is movable clockwise against the bias of spring 62 to the dot-dash line, unlatching and actuated position A in FIG. 31. Rubber bumper 364 in FIGS. 31 and 40 encircles lug 340c integral with and struck-up from plate portion 340a and is adapted to resiliently stop this counterclockwise movement of lever 356 before pawl 356b strikes with a clicking sound between adjacent teeth of ratchet 346 so that the lock will be silent in operation. Integral stop arm 356c of pawl lever 356 is adapted to travel in and along the length of slot 340mn in plate portion 340b.

As to this lock 310, position K2 in FIGS. 25-27 is the locked or actuated position L and position K1 is the unlocked or actuated position UL. Key link 24, pivotally connected to lever 354, is shown in FIG. 31 in its actuated unlocking position K1 and is adapted to be moved downwardly by key actuated link 24, in the manner previously described, to an actuated locking position K2, shown in solid lines in FIG. 33, with locking lever 354 swinging counterclockwise about pivot 357 from its unlocked position UL to locked position L. Toggle spring 366 is pivotally connected at opposite ends to plate portion 340a and locking lever 354 to maintain the lever 354

in either of these two positions L or UL by having the spring end connected to lever 354 swing over center with respect to pivot 357 and the other spring end. These two positions L and UL of lever 354 are determined by the engagement of the stop arm 354a of locking lever 354 with the lower end of slot 340mn in plate portion 340b through which it travels to determine position UL in FIG. 32 and by engagement of pawl 356b with the root diameter between adjacent teeth of ratchet 346 in FIG. 33 to determine position L. This cam face 354b is also adapted to engage or disengage a tooth of ratchet 346 at suitable times in the lock operation.

The outside handle 30 through its link 32 in FIGS. 25, 26 and 31 controls some functions of the lock. Link 32 is shown in FIG. 31 in its solid line or unactuated position OUA, but as it moves upwardly to its dot-dash line or actuated position OA, it swings release lever 372, to which it is pivotally connected by rivet 369, clockwise about rivet formed pivot 374 by which lever 372 is pivotally connected to plate portion 340a.

It should be noted that a linkage operatively connects locking lever 354, pawl lever 356 and release arm 372 in FIGS. 31, 39 and 41. A rotor releasing toggle link 376 is pivotally connected at its upper end by rivet 378 to pawl lever 356 in FIG. 31, a toggle link 380 is pivotally connected at its lower end in FIG. 33 by rivet 382 in FIG. 41 to release arm 372, and a control link 384 is pivotally connected in FIG. 33 at its right end by pivot 386 in FIG. 39 with locking lever 354. The links 376, 380 and 384 are interconnected remote from the previously described pivots by a pivot 388 in FIGS. 33, 39 and 41 extending from link 384 through a slot 376a in toggle link 376 and pivotally connected to toggle link 380. The control link 384 and its pivots 386 and 388 are formed of a continuous length of rod or wire stock with bent over ends, as shown in FIG. 39, but may be alternately formed as a strip type strap, like link 184. The bent over end forming pivot 388 extends through a hole in toggle link 380 and through slot 376a in toggle link 376 to be peened on the right-hand side thereof in FIG. 39. Pivot 386 is formed by having the bent over end of the wire forming control link 384 extend through a hole in locking lever 354 while a C-washer, clamping ring or snap ring 390 is snapped into a groove in control link 384 on the righthand side of locking lever 354 in FIG. 39.

In FIGS. 1, 30 and 32, lock 310 also has parts actuated by inside handle 26 through link 28. Remote control link 28 is pivotally connected at its left end in FIG. 32 to remote lever 394 by rivet 395 and lever 394 is pivotally connected by rivet 396 to remote plate portion 340b. As the inside front door handle 26 swings clockwise in FIGS. 1 and 30, it moves link 28 toward the left in FIGS. 1 and 32 and swings remote lever 394 clockwise in FIG. 32 about rivet 396 from an actuated or door unlatched position IA to a neutral, latched or unactuated position IUA and then to a locked position IL.

Lock 310 has a lever 394 with integral arms 394a and 394b. Arm 394a is adapted to move stop arms 354a and 356c from the top to engagement with the bottom of their slot 340mn as lever 394 swings counterclockwise from locked position IL through neutral position IUA to actuated position IA so as to push arm 354a from locked position L to unlocked position UL and to push arm 356c from unactuated position UA to actuated position A. Arm 394b is adapted to push stop arm 354a from the unlocked position UL in FIG. 32 at the bottom of slot 340mn to the locked position L in FIG. 34 at the top of slot 340mn as lever 394 swings clockwise from unactuated position IUA to locked positions IL.

Spring washers may be put on any one or all of the rivets wherever desired in any of these four locks to make the locks substantially noiseless in operation.

MODE OF OPERATION OF LOCK IN FIGS. 30-41

The operation of this lock and door will now be described in detail.

Door 14 in FIGS. 30-32 and 37-39 is in its closed position with the lock 310 in its unlocked position UL and latched or unlatched position UA and with the inner and outer door handles 26 and 30 in their unlatched positions IUA and OUA in the solid line with stop arms 354a and 356 limit stopped against the lower end of slot 340mn and against rubber bumper 364 respectively in FIGS. 32 and 31. Then, door 14 is kept in its closed position and prevented from swinging on hinges 14a outwardly to the open position by the pawl lever 356 being urged counterclockwise about pivot 357 in FIG. 31 into its solid line, unlatched position UA by the spring 362 to keep pawl 356b in latching position between adjacent teeth of ratchet 346 with pawl face 356r latched against one of the teeth. Since swinging of door 14 to its open position requires rotor housing 342 in FIG. 38 to move toward the left relative to the relatively stationary striker 318, any opening movement will tend to rotate rotor 320 clockwise in FIG. 38 and to rotate ratchet 346 clockwise in FIG. 31. Integral pawl face 356r of pawl 356b on pawl lever 356 engages in unlatched position UA with the clockwise side of a tooth on ratchet 346 to prevent this clockwise rotation of ratchet 346 to keep the door in its closed position since spring 362 urges pawl lever 356 counterclockwise into this latching position.

To open the door 14 so that it may swing from the door closed to the door open position, one need merely move either the inside or outside handle 26 or 30 from its unlatched position IUA or OUA to actuated position IA or OA so as to swing pawl lever 356 clockwise about pivot 357 in FIG. 31 and to move pawl 356b and the other component parts from their solid line, latched, unlatched positions UA in FIG. 31 to their actuated or unlatched dot-dash line positions A in FIGS. 31 and 32. Inside handle 26 is swung counterclockwise in FIG. 1, link 28 is pulled toward the right from the solid line unlatched position IUA to the dot-dash line actuated position IA in FIG. 32 so that lever arm 394a is swung counterclockwise in FIG. 32 from the solid line position to the dot-dash line position to engage stop arm 356c and swing pawl lever 356 clockwise in FIG. 31 about pivot 357 to swing pawl 356b and its pawl face 356r outwardly to the dot-dash line position A to travel from the latched or unlatched position UA to the unlatched or actuated position A and stop arm 356c limit stops against the lower end of slot 340mn in FIG. 32. If stop arm 354a has been in the locked position L at the upper end of slot 340mn in FIG. 34, arm 394a will carry it to the unlocked position UL at the lower end of slot 340mn in FIG. 32. Then, ratchet 346 is free to rotate so that rotor 320 in FIG. 38 may rotate clockwise and will be permitted to move toward the left in FIG. 38 so that the door 14 may be swung to its open position. If the lock 310 is to be unlatched by the outside handle 30, one must swing outside handle 30 outwardly in FIG. 25 from its unlatched position OUA to its actuated position OA to move link 32 upwardly from the solid to dot-dash line position in FIG. 31 to swing release arm 372 clockwise about pivot 374, and toggle link 380 will push toggle link 376 upwardly in FIG. 31 by pivot 388 engaging the upper end of slot 376a to swing pawl lever 356 clockwise about pivot 357 against the bias of spring 362 so as to swing pawl 356b and its pawl face 356r from the latched, unlatched position UA to the unlatched, actuated position A and thus move all of these parts from solid line position UA to dot-dash line position A in FIG. 31 so that ratchet 346 is free to rotate and the door will open in the same manner.

After the door has swung outwardly to its open position, it may be swung or slammed closed without touching either the inside or outside handle 26 or 30. After the door has opened and the door opening handle 26 or

30 has been released, pawl 356b will be biased counterclockwise in FIG. 31 from the dot-dash line actuated position A to the solid line unlatched position UA by spring 362 so as to move from the unlatched to the latched position. When the door 14 is swung from its open to its closed position, the lock and its rotor body 342 will move toward the right in FIG. 38 relative to the relatively stationary striker 318 so that the travel of rotor 320 under the striker 318 will cause the rotor 320 to rotate counterclockwise as the door moves toward its closed position. As rotor 320 rotates counterclockwise, ratchet 346 in FIG. 31 rotates counterclockwise so that the teeth thereof successively force the pawl lever 356 to oscillate about pivot 357 by their individual engagements with the pawl face 356s of the pawl 356b until the door is fully closed. Then, spring 362 again biases the pawl lever 356 counterclockwise until pawl 356b is firmly seated in its latching or unlatched position UA between adjacent teeth of ratchet 346 with pawl face 356r latched firmly against a ratchet tooth. Note that slot 376a merely reciprocates back and forth over pivot 388 so that release arm 372 and outside handle 30 are not moved out of unlatched position OUA by the door closing action.

In lock 310, when the number and design of teeth in rotor 320 is so chosen that it is desirable to exert an upward force in FIG. 38 on the lock and rotor housing 342 to properly seat the rotor 320 against the striker, wedge 350 with its compression spring 352 is preferably used. Then, as the rotor housing 342 telescopes over the relatively stationary striker 318 in FIG. 38, beveled surface 318a of the striker 318 in FIG. 38 will coat with beveled surface 350a of the wedge 350 to wedge the lock and rotor housing 342 upwardly as the door moves toward its fully closed position against the compression of spring 352 so that the proper coaction will take place between the teeth of striker 318 and rotor 320 so that no vertical motion of the door will be allowable.

Lock 310 may be moved to its locked position L in FIGS. 33 and 34 by inside handle 26. When inside handle 26 is in its neutral, unlatched and unlocked position IUA, remote lever 394 is in the solid line position of FIG. 34. As inside handle 26 is swung clockwise in FIG. 1 to the locked position IL, remote control link 28 is moved toward the left in FIGS. 1 and 30 and remote control lever 394 is swung clockwise in FIG. 34 from the solid line unlatched position IUA to dot-dash line locked position IL so that arm 394b moves stop arm 354a from the lower end of slot 340mn upwardly toward the upper end of slot 340mn from the solid line unlocked position UL in FIGS. 31 and 32 to the solid line locked position L in FIGS. 33 and 34 to swing locking lever 354 counterclockwise from the solid line position UL in FIG. 31 to the solid line position L in FIG. 33 until locking lever cam face 354b bottoms against the root between adjacent teeth of rotor 346 so as to pull toggle links 376 and 380 to the solid line position in FIG. 33 by control link 384. Locking lever 354 is movable between positions UL and L without key actuated movement of the tumblers of lock key cylinder 22 because (1) lug 22a is in the neutral or unlatched position KN in FIG. 27 since the key has been turned it to this position prior to key removal from lock key cylinder 22, and (2) the vertical size of slot 25a in FIG. 27 permits bell crank 25 to move from unlocked position K1 to locked position K2 without movement of lug 22a from neutral or unlatched position KN and without key actuation of the tumblers of lock key cylinder 22. Now, the lock is in the locked position L and it is impossible to unlatch the lock and open the door by the outside handle 30. If the outside handle 30 is swung outwardly in FIG. 25 from its unlatched position OUA to its actuated position OA so as to move outside handle link 32 upwardly from the solid line to the dot-dash line position in FIG. 33, pivot 388 will merely travel between the solid line and dot-dash line position in FIG. 33 in slot 376a but will not cause disengagement of pawl 356b from between the teeth of ratchet 346 so as to move it from

the latched or unlatched position UA to the unlatched or actuated position A in FIG. 31 to permit door opening. After inside handle 26 has been manually actuated to move lever 394 from solid line position IUA to dot-dash line position IL in FIG. 34 to lock the door and then inside handle 26 is released, spring 27 in FIG. 1, pushing against arm 26a, will return handle 26 in a counterclockwise direction to the neutral position IUA and lever 394 to its solid line neutral position IUA in FIG. 34.

In lock 310, suitable construction therein also prevents unauthorized entry of the automobile by an intruder through the unlocked door if the car occupant quickly manipulates the inside handle 26. The occupant may be safe even if the intruder has had time to move the outside handle 30 to the fully actuated position OA, has withdrawn pawl 356b from the latching or unlatched position UA between adjacent teeth of ratchet 346 to unlatching or actuated position A, and the rotor 320 has rotated $\frac{1}{6}$ of a rotation clockwise in FIG. 38 to partially open the door to the safety position with the rotor 320 held between the first and second tooth from the left in FIG. 38 on striker 318. If the occupant grabs the inside handle 26 and swings it clockwise in FIG. 1 to the locked position IL before rotor 320 has left the safety position, this movement of handle 26 will swing lever 394 clockwise to the dot-dash line position IL in FIG. 34 to lock the door by swinging locking lever 354 from unlocked position UL in FIG. 32 to locked position L in FIG. 34. This movement of lever 354 causes control link 384 to move pivot 388 toward the right to break the toggle formed by toggle links 376 and 380 by moving them to the solid line position of FIG. 33 so as to break the operative connection formed by the rigid toggle links 376 and 380 in FIG. 31 between outside handle 30 and latching pawl 356b. Then, spring 362 will rotate pawl lever 356 counterclockwise to the solid line or unlatched position UA in FIG. 33 to snap its pawl face 356r into latching engagement between adjacent teeth of and with a tooth of ratchet 346. This locking action will automatically take place independently of the position of outside handle 30; and once the door is locked, the outside handle 30 may be freely moved between unlatched and actuated positions OUA and OA without opening the door. Note that the car occupant can hold the door closed and lock the door by grasping only one inside handle 26, by both hands if necessary; and need not hold the door closed by grasping the handle with one hand while trying to actuate a separate inside lock button with the other.

The door may also be locked from outside the automobile by the use of a key in the lock key cylinder 22. When the proper key is inserted in the lock 22 in FIGS. 25 and 26 and is rotated counterclockwise in FIG. 27, the tumbler actuated lug 22a of the lock cylinder 22 will rotate counterclockwise in FIG. 27 from position KN to position K2 to lower link 24 from the unlocked, solid line position K1 in FIG. 31 to the actuated, locking, and solid line position K2 in FIG. 33 to move the component parts of the lock from the solid line, unlocked, position UL in FIG. 31 to the solid line, locked position L in FIG. 33 to lock the door. Then, pivot 388 will be pulled toward the right by control link 384 and will move toggle links 376 and 380 to the solid line position in FIG. 33 to provide the same locking action as mentioned in regard to inside handle 26.

In lock 310, the door may be unlocked by key or by manual actuation of inside lever 26. If the key is inserted into lock 22 and is turned clockwise in FIG. 27 from neutral position KN to unlocked position K1, link 24 is forced upwardly from the locked dot-dash line position K2 in FIG. 26 and locked solid line position L in FIG. 33 to the actuated unlocking solid line position UL in FIG. 31 and position K1 in FIG. 26. If inside handle 26 is swung counterclockwise in FIG. 1 from unlatched position IUA to actuated position IA, it swings lever 394 counterclockwise from the solid line position IUA in FIG.

32 toward the dot-dash line position IA to move arm 354a between the positions L and UL in these drawing figures.

With lock 310, if outside handle 30 is jammed by a crash or for any other reason in actuated position OA, unlatched position OUA, or any intermediate position, while locked or unlocked, the car occupant will still be able to open the door. Pawl 356b may be unlatched at any time by moving inside handle 26 counterclockwise in FIG. 1 to the actuated position IA, and this motion will move lever 354 to unlocked position UL, if it is in locked position L, and will move pawl 356b to its unlatched or actuated position A independently of the location of outside handle 30.

Automatic delocking is a feature of lock 310. If the door 14 is swung to its open position, locked by either inside handle 26 or by key actuation of lock key cylinder 22, and then the door 14 is swung to its closed position without touching either handle 26 or 30, the lock 310 will operate properly, the lock 310 will be in unlocked position UL when closed, and the door can be then opened by outside handle 30. This locking action will move the lock parts to the solid line, locked position L of FIG. 33 in the manner previously described. Swinging the door to its closed position will automatically delock rotor 320 of the lock 310 and move the parts to the solid line, unlocked position UL of FIG. 31. As the door 14 moves toward the closed position, the lock and its rotor housing 342 in FIG. 38 will move toward the right relative to relatively stationary striker 318 so that rotor 320 rotates counterclockwise and this causes ratchet 346 to rotate counterclockwise in FIGS. 31 and 33 so that the component lock parts move from the solid line position in FIG. 33 through the dot-dash line position in FIG. 35 to the solid line positions in FIG. 31. Counterclockwise rotation of ratchet 346 performs two functions. First, cam face 354b, providing a lever arm about pivot 357, is forced, by the immediately clockwise located tooth profile of ratchet 346, upwardly in FIGS. 33 and 35 to rotate locking lever 354 in a clockwise direction from the solid line, locked position L in FIG. 33 through the solid line position in FIG. 35 to the solid line, unlocked position UL in FIG. 31 to automatically unlock the lock by pushing pivot 388 toward the left to straighten the toggle formed by links 376 and 380 by moving them between the solid line positions of FIGS. 33 and 31. Locking lever 354 is movable between positions L and UL without key actuated movement of the tumblers of lock key cylinder 22 because (1) lug 22a is in the neutral or unlatched position KN in FIG. 27 since the key has returned it to this position prior to key removal from lock key cylinder 22, and (2) the vertical size of slot 25a in FIG. 27 permits bell crank 25 to move from locked position K2 to unlocked position K1 without movement of lug 22a from neutral or unlatched position KN and without key actuation of the tumblers of lock key cylinder 22. Second, counterclockwise rotation of ratchet 346 causes the immediately clockwise located tooth profile of the ratchet to act against pawl face 356a of pawl 356b to swing pawl lever 356 about pivot 357 in a clockwise direction against the resilient bias of spring 362 from its unlatched, latching position UA toward its actuated, unlatching position A so that rotor 320 may rotate properly and let the door move fully to its closed position at which time spring 362 returns pawl lever 356 in a counterclockwise direction to urge the pawl 356b inwardly between adjacent teeth of ratchet 346 to latched or unlatched position UA. Now, actuation of outer handle 30 will open the door since unlocking has occurred.

It should be noted that if the door 14 is open, the door is locked and outside handle 30 is swung to its actuated position OA, as shown by the dot-dash lines in FIG. 33, the lock 310 will still properly operate when the door is slammed to its closed position while the outside handle 30 is held in its actuated position OA and the unlocked door then can be opened from the outside by

handle 30. As the door moves toward its closed position, the lock parts are in the dot-dash line or actuated position OA of FIG. 33 with pivot 388 near the upper end of slot 376a in FIG. 33 but not against it. As the counterclockwise rotation of the ratchet 346 causes the parts to move through the solid line position of FIG. 35, the outside handle 30 will remain substantially in its actuated position OA because of the design of links 376, 380 and 384. If there is any tendency to urge release arm 372 in the counterclockwise direction in FIG. 33 or 35 to move the outside handle 30 back toward its unactuated position OUA, there will be sufficient give in spring 362 to permit the outside handle 30, if sufficient pressure is applied thereto, to remain in its actuated position OA. Also, as the parts approach the dot-dash line or actuated position OA in FIG. 31, the pivot 388 should preferably engage against the upper end of slot 376a so as to forceably move pawl lever 356 clockwise about pivot 357 against the bias of spring 362 to swing the pawl 356b outwardly toward its actuated or unlatched position A beyond the outer edge of the teeth of ratchet 346 because the ratchet 346 should be preferably in a free wheeling position when the door is in unlocked position UL and the outside handle 30 is in its actuated position OA in the manner shown by dot-dash lines in FIG. 31 so that the door will easily open when the outside handle 30 is actuated. Also, cam face 354b is forced out by a tooth profile on ratchet 346 to rotate the locking lever 354 clockwise to unlock the lock by swinging lever 354 to unlocked position UL to push pivot 388 toward the left by control link 384. Hence, the lock 310 will be automatically moved to unlocked position UL as the door closes by moving the lock parts from the locked position L of FIG. 33 to the unlocked position UL of FIG. 31 through the FIG. 35 position whether the outside handle 30 is in actuated position OA, unactuated position OUA, or an intermediate position, and the lock 310 may be unlatched by actuating outside handle 30 to move cam 356b to an actuated and unlatched position A.

The door may also be easily locked from the outside by inserting the proper key in cylinder lock 22 after the door has been moved to its fully closed position. Then, rotation of the key counterclockwise in FIG. 27 will move lug 22a from position KN to position K2 to cause the parts to assume the locked position K2 in FIGS. 25 and 26 and the locked position L in FIG. 33. Then, the outside handle 30 is free to move between its positions OA and OUA or may have an idling action, and this movement will not unlatch the door as the operator moves it between unactuated position OUA and actuated position OA. During this movement, release arm 372 oscillates around pivot 374 so that release lever link 380 moves pivot 388 back and forth along the length of slot 376a. However, this lost motion movement of pivot 388 in slot 376a should preferably be restricted by a suitable end stop, formed by engagement of stop portions 14d and 30a in FIG. 25, limiting the movement of outside handle 30 and link 32 within a desirable range. For example, it is preferred that when the outside handle 30 is in its actuated position OA, as shown in dot-dash lines in FIG. 33, and these stop positions 14d and 30a are engaging, a gap 376b will still remain between pivot 388 and the upper end of slot 376a so that anyone attempting to unlock the door will not be able to begin to move pawl 356b even slightly out of its fully latched or unactuated position UA shown in FIG. 33.

As to gap 376b, it should also be apparent that when the door is locked, with the parts in the solid line position of FIG. 33, the outside handle 30 may be moved between actuated and unactuated positions OA and OUA, shown by dot-dash and solid line positions in FIG. 33, without causing damage to the lock components.

The construction and coaction of control link 384 coacting with slot 376a and toggle links 376 and 380 controls the delocking and locking action, controls the toggle

action, prevents the toggle from swinging over center in the leftward direction, prevents unauthorized unlatching movement of pawl 356b from unactuated position UA by actuation of outside handle 30 after the door is closed and locked, permits door slamming without disturbing the outside handle 30 in the unactuated position OUA, enables the occupant to prevent the entry of intruders, permits the door to be opened from the inside by movement of inside handle 26 to actuated position IA even when the outside handle 30 is jammed in any position, and permits the lock to have all desirable operating characteristics.

In FIGS. 30-41, there has been disclosed a lock or latch mechanism 310 having latch means including rotor 15 320 for latching cooperation with keeper means or striker 318, detent means or pawl lever 356 pivotally mounted on an axis formed by pivot 357 and cooperable with the ratchet 346 of the latch means for releasably detaining such latch means in latching cooperation with the keeper 20 means, manually operable control means including outside handle link 32, means, including links 376, 384 and 388, operatively connecting said control means with said detent means and movable into one position shown as unlocked position UL for release actuation of said 25 detent means upon manual operation of said control means with consequent release of said latch means and into another position shown as locked position L for preventing said release actuation by said manual operation, and a lever 354 pivotally connected on the axis 30 formed by pivot 357 and responsive to relative movement between said latch means and keeper means during door closing for automatically moving said connecting means from said other position L to said one position UL. Also, the axis of said detent means and the axis 35 of said lever are coaxial on pivot 357, ratchet 346 of said latch means has a plurality of circumferentially arranged teeth, said detent means has a pawl portion 356b engageable with said latch means between a pair of adjacent teeth, and said lever 354 has a cam face portion 354b engageable with said latch means between the same pair of adjacent teeth in FIG. 33.

Various changes in details and arrangement of parts can be made by one skilled in the art without departing from either the spirit of this invention or the scope of the 45 appended claims.

What is claimed is:

1. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means, and means for breaking said toggle to thereby permit operation of said control means without release actuation of said detent means.
2. Latch mechanism, comprising latch means for latching cooperation with keeper means, detent means cooperable with the latch means for releasably detaining such latch means in latching cooperation with the keeper means, outside manually operable control means, means operatively connecting said control means with said detent means for release actuation of said detent means upon manual operation of said control means with consequent release of said latch means, a toggle in said connecting means, and means for breaking said toggle to thereby permit operation of said control means without release 60 actuation of said detent means.
3. Latch mechanism for a door movable between open and closed positions, comprising latch means for latching cooperation with keeper means, detent means cooperable with the latch means for releasably detaining such 75

latch means in latching cooperation with the keeper means, manually operable control means, means operatively connecting said control means with said detent means for release actuation of said detent means upon manual operation of said control means with consequent release of said latch means, a toggle in said connecting means, means for breaking said toggle, and means responsive to door closing movement and resulting interengaging relationship of the latch means and the keeper means for automatically straightening said toggle.

4. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means, means for breaking said toggle, and means responsive to interengaging relationship of said latch means and said keeper means for automatically straightening the toggle.

5. Latch mechanism, comprising latch means for latching cooperation with keeper means, detent means cooperable with the latch means for releasably detaining such latch means in latching cooperation with the keeper means, inside and outside manually operable control means, means operatively connecting each of said control means with said detent means for release actuation of said detent means upon manual operation of said control means with consequent release of said latch means, a toggle in said connecting means operatively connecting said detent means and outside manually operable control means, and means for breaking said toggle to thereby permit operation of said outside control means without release actuation of said detent means.

6. Latch mechanism, comprising latch means for latching cooperation with keeper means, detent means cooperable with the latch means for releasably detaining such latch means in latching cooperation with the keeper means, inside and outside manually operable control means, means operatively connecting each of said control means with said detent means for release actuation of said detent means upon manual operation of said control means with consequent release of said latch means, a toggle in said connecting means operatively connecting said detent means and outside manually operable control means, and means responsive to movement of said inside manually controllable means for breaking said toggle to thereby permit operation of said outside control means without release actuation of said detent means.

7. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means with a pivot pin and slot connection intermediate the toggle ends, and means for breaking said toggle to thereby permit operation of said control means without release actuation of said detent means.

8. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means to an actuated position with consequent release of said latch means, a toggle in said connecting means with a pivot pin and slot

connection intermediate the toggle ends with the toggle movable between broken and straightened positions, said slot connection being so constructed that said pivot pin does not engage an end of said slot with said toggle in broken position and said control means in said actuated position, and means for breaking said toggle to thereby permit operation of said control means without release actuation of said detent means.

9. Latch mechanism, comprising latch means for latching cooperation with keeper means, detent means pivotally mounted on an axis and cooperable with the latch means for releasably detaining such latch means in latching cooperation with the keeper means, manually operable control means, toggle means operatively connecting said control means with said detent means and movable into one position for release actuation of said detent means upon manual operation of said control means with consequent release of said latch means and into another position for preventing said release actuation by said manual operation, and a lever pivotally connected on an axis and responsive to interengaging relationship of said latch means and said keeper means for automatically moving said connecting means from said other to said one position.

10. Latch mechanism, comprising latch means for latching cooperation with keeper means, an outside manually operable control means for releasing said latch means from latching cooperation with said keeper means, an inside manually operable control means for releasing said latch means from latching cooperation with said keeper means, and toggle means responsive to toggle breaking movement of the inside control means for preventing the release of said latch means from latching cooperation with said keeper means in any operated position of said outside control means.

11. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means with the toggle movable between broken and straight positions, and means for breaking said toggle in any detent position to thereby permit operation of said control means without release actuation of said detent means.

12. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means to an actuated position with consequent release of said latch means, a toggle in said connecting means with the toggle movable between broken and straight positions, said toggle being in its straight position for release actuation of said detent means, and means for moving said toggle between its said positions while said control means remains substantially in said actuated position.

13. Latch mechanism, as set forth in claim 9, wherein said axis of said detent means and said axis of said lever are coaxial, said latch means has a plurality of circumferentially arranged teeth, said detent means has a portion engageable with said latch means between a pair of adjacent teeth, said lever has a portion engageable with said latch means between the same pair of adjacent teeth.

14. Latch mechanism, as set forth in claim 9, wherein said axis of said detent means and said axis of said lever are coaxial, said latch means has a plurality of circum-

ferentially arranged teeth, said detent means has a portion engageable with said latch means between a pair of adjacent teeth, said lever has a portion engageable with said latch means between a different pair of adjacent teeth.

15. Latch mechanism, as set forth in claim 9, wherein said axis of said detent means and said axis of said lever are spaced laterally apart, a reciprocatable slide is operatively connected to said lever for moving said lever between said positions, said slide including a closed end slot with a lug on one edge of said slot, another manually operable control means including a pivoted lever for release actuation of said detent means and for engagement with said lug to move said slide from said other to said one position.

16. Latch mechanism, as set forth in claim 9, wherein said axis of said detent means and said axis of said lever are spaced laterally apart, a reciprocatable slide is operatively connected to said lever for moving said lever between said positions, said slide having a peripheral edge with a lug located thereon, another manually operable control means including a pivoted lever for release actuation of said detent means and for engagement with said lug to move said slide from said other to said one position.

17. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means including two toggle links and pivot means pivotally connecting said links together, and means operable on said pivot means for breaking said toggle to thereby permit operation of said control means without release actuation of said detent means.

18. Latch mechanism, comprising latch means for latching cooperation with keeper means, detent means cooperable with the latch means for releasably detaining such latch means in latching cooperation with the keeper means, outside manually operable control means, means operatively connecting said control means with said detent means for release actuation of said detent means upon manual operation of said control means with consequent release of said latch means, a toggle in said connecting means and outside key actuated means operatively connected to said toggle intermediate its ends for breaking said toggle to thereby permit operation of said control means without release actuation of said detent means.

19. Latch mechanism for a door movable between open and closed positions, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means, means for breaking said toggle and means responsive to door closing movement and resulting interengaging relationship of the latch means and the keeper means for automatically straightening said toggle by exerting a force on said toggle intermediate its ends.

20. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon

manual operation of said control means with consequent release of said latch means, a toggle in said connecting means, means for breaking the toggle, and means operatively connected to said toggle intermediate its ends and responsive to interengaging relationship of said latch means and keeper means for automatically straightening the toggle.

21. Latch mechanism, comprising latch means for latching cooperation with keeper means, detent means cooperable with the latch means for releasably detaining such latch means in latching cooperation with the keeper means, inside and outside manually operable control means, means operatively connecting each of said control means with said detent means for release actuation of said detent means upon manual operation of said control means with consequent release of said latch means, a toggle comprising two pivotally connected toggle links in said connecting means operatively connecting said detent means and outside manually operable control means, 20 and means for breaking said toggle by moving said pivot of said toggle links to thereby permit operation of said outside control means without release actuation of said detent means.

22. Latch mechanism, comprising latch means for latching cooperation with keeper means, detent means cooperable with the latch means for releasably detaining such latch means in latching cooperation with the keeper means, inside and outside manually operable control means, means operatively connecting each of said control means with said detent means for release actuation of said detent means upon manual operation of said control means with consequent release of said latch means, a toggle in said connecting means operatively connecting said detent means and outside manually operable control means, and means responsive to movement of said inside manually operable control means in a non-latch means releasing direction for breaking said toggle to prevent release actuation of said detent means by operation of said outside control means.

23. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means with a pivot pin and slot connection intermediate the toggle ends, and means operatively connected to said pivot pin for breaking said toggle to thereby permit operation of said control means without release actuation of said detent means.

24. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means to an actuated position with consequent release of said latch means, a toggle in said connecting means with a pivot pin and slot connection intermediate the toggle ends with the toggle movable between broken and straightened positions, said slot connection being so constructed that said pivot pin does not engage an end of said slot with said toggle in broken position and said control means in said actuated position, and means operatively connected to said pivot pin for breaking said toggle to thereby permit operation of said control means without release actuation of said detent means.

25. Latch mechanism, comprising latch means for latching cooperation with keeper means, detent means pivotally mounted on an axis and cooperable with the

latch means for releasably detaining such latch means in latching cooperation with the keeper means, manually operable control means, toggle means operatively connecting and control means with said detent means and movable into a straightened position for release actuation of said detent means upon manual operation of said control means with consequent release of said latch means and into a broken position for preventing said release actuation by said manual operation, a lever pivotally connected on the same axis as said detent means, and operating means for said lever responsive to interengaging relationship of said latch means and keeper means for automatically moving said connecting means from said other to said one position.

26. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means with consequent release of said latch means, a toggle in said connecting means with the toggle movable between broken and straight positions, and means for breaking said toggle in

20
25

any detent position to prevent release actuation of said detent means by operation of said control means.

27. Latch mechanism, comprising latch means for latching cooperation with keeper means, detent means cooperable with the latch means for releasably detaining such latch means in latching cooperation with the keeper means, manually operable control means, means operatively connecting said control means with said detent means for release actuation of said detent means upon manual operation of said control means to an actuated position with consequent release of said latch means, a toggle in said connecting means including two toggle links and pivot means pivotally connecting said links together and with the toggle movable between broken and straight positions, and means connected to said pivot means for moving said toggle between its said positions while said control means remains substantially in said actuated position.
